ABSTRACT

An improved reproduction system for making duplicates from an original having a printing cylinder provided with a clamp for selectively receiving, holding or ejecting a master, a take-up assembly adapted to cooperate with an eject mode of cylinder clamp operation to receive a discharged master, an original and master material feeding assembly adapted to bring the original and master into registry and carry the sandwiched original and master material into an imaging assembly to make a duplicating master, a transfer assembly adapted to transfer the imaged master toward the cylinder clamp, and the latter operating in a receiving mode adapted to draw the master to the printing cylinder, and to hold the imaged master during a print mode of cylinder operation in which reproductions are made. The system has controls for programming the machine through respective preparation, function and print cycles.

DUPLICATING SYSTEMS WITH SHEET HANDLING FEATURES

This is a division of application Ser. No. 98,260, filed Dec. 15, 1970, now U.S. Pat. No. 3,788,221.

BACKGROUND OF THE INVENTION

The art has generally recognized a difference between copying and duplicating processes. Briefly, copying involves a process in which a reproduction is made from an original without requiring an intermediate sheet. Examples are electrostatic copying processes that fix the image on an exposed photosensitive copy sheet, or develop an image on a photosensitive insulating surface and transfer the image to an ordinary paper sheet and fix the image thereon; and thermographic copying processes which use a heat sensitive sheet imaged in areas of high heat application. Duplicating, on the other hand, involves a process in which a master sheet or plate is first formed and then used to make the reproductions. Examples are offset duplicating processes in which image areas on the master are made ink receptive so as to effect ink transfer to a reproduction sheet, mimeographic duplicating processes in which image areas on the master permit ink to seep through and be impressed on a reproduction sheet, and spirit duplicating processes where a dye transfers to a moistened reproduction sheet from the reverse image areas on the master to effect image formation on the reproduction sheet.

An example in the prior art of a systems approach to combining copying and duplicating operations is Carper et al. U.S. Pat. No. 3,426,678 issued Feb. 11, 1969. That system utilizes an offset master for the duplicating process which is made by copying the original using an electrostatic process. It does not suggest the system contemplated in the present invention, and more specifically, it does not suggest combining a mimeograph duplicating process with any other copying process to realize the advantages of the mimeographic process.

The use of thermography to make a copy is known. Examples of the practice of the process are described in co-pending Bach U.S. Application Ser. No. 878,049 filed Nov. 19, 1969, now Pat. No. 3,632,208 assigned to A. B. Dick Company, the assignee of the present application and my co-pending U.S. Pat. application Serial No. 71,619 titled: "Improved Thermal Imaging Method," filed September 11, 1970, also assigned to A. B. Dick Company and now abandoned.

The manufacture of equipment and supplies for practicing the mimeograph process for duplicating on a variety of mediums has been the business of A. B. Dick Company during all of its long history. As is well known, the process uses ink either in liquid or paste form carried in one instance by a cylinder which has a master or stencil wrapped about its periphery permitting selective release of the ink through to a copy sheet to form a desired image thereon. The mimeograph process is well known as versatile, reliable and economical.

It is also known in the art that a mimeograph stencil or master can be made by various procedures, mechanically as with a typewriter, electronically or thermographically. (For the latter see Hoover U.S. Pat. No. 2,699,113 and Roshkind U.S. Pat. No. 2,808,777 both assigned to the A. B. Dick Company.) Some materials used to thermographically form a stencil are not easy to handle, and there is no known system for automati-

cally loading into, and ejecting from a mimeograph cylinder either a thermographically formed mimeograph stencil or stencils formed by the other methods.

SUMMARY OF THE INVENTION

Accordingly, it is an object of the present invention to provide an improved system in which a reproduction master is automatically loaded on, or ejected from a printing form.

It is a further object of the present invention in accordance with the above to provide an integrated system for imaging a mimeograph stencil or master by using an original, automatically ejecting a used master and loading a newly imaged master and making the desired number of reproductions.

It is an additional object in accordance with the above to provide an improved system for facilitating transporting of a pair of sandwiched sheets, for example, a juxtaposed original and a stencil, and separating of the two sheets to direct them along two predetermined paths.

It is yet another object of the present invention to provide a system for ejecting and storing a sheet such as a used mimeograph stencil without soiling either an operator or surrounding equipment.

It is a more detailed object of the present invention in accordance with the above to provide a reproduction system which maintains the integrity of the stencil or master after it is ejected for possible reuse.

It is another detailed object of the present invention to provide a system for ejecting a used mimeograph stencil, thermally imaging a new stencil with a juxtaposed original, separating the original and stencil or master, loading the latter on a mimeograph printing form, and duplicating a desired number of reproductions.

It is an overall object of the present invention to provide an improved economical, reliable and efficient reproduction system for making either one or more copies of an original which allows use of a wide range of different recording mediums, including commonly available non-proprietary papers.

FIG. 19 is an enlarged side elevation showing an actuating mechanism for the cam assembly of FIG. 18;

FIG. 20 is a plan view partially in section of the actuating mechanism of FIG. 19;

FIG. 21 is a side elevation of the cam for controlling cylinder rotation of FIG. 17 and the mechanism for actuating the same;

FIG. 22 is a plan view, partially in section, showing cams, timing switches and the pneumatic system associated with the mimeograph cylinder;

FIG. 23 is an elevation as viewed along line 22—22 in FIG. 21;

Figs. 24A, 24B and 24C are stop motion diagrams to show steps in the separation or stripping of the original and stencil and transfer of the latter to the mimeograph cylinder;

FIG. 25 is an elevation with portions removed to show the angular relationship of the timing switches of FIG. 22;

FIG. 26 is another elevation emphasizing some of the details of the mounting of the timing switches of FIG. 25;

FIG. 27 is an elevation of a master cam assembly for controlling machine operation;

FIG. 28 is a section taken along line 28—28 in FIG. 27 showing details of the master cam of FIG. 27;

FIG. 29 is a diagrammatic representation of the drive system for the copier/duplicator;

FIG. 30 is an elevation showing a speed selector in the drive system of FIG. 29;

FIG. 31 is an elevation showing the drive train for selectively varying the thermal imaging speed in the drive system of FIG. 29;

FIG. 32 is a fragmentary view taken on line 32—32 in FIG. 31 of a drive speed selector for the drive train of FIG. 31;

FIG. 33 is a first portion of an electrical schematic for the copier/duplicator;

FIG. 34 is a second portion of the electrical schematic for the copier/duplicator connected to the schematic of FIG. 33;

FIG. 35 is a sequence diagram showing a preparation cycle for the copier/duplicator; and

FIG. 36 is a related sequence diagram showing a function cycle and a print cycle.

GENERAL DESCRIPTION

Referring now to the drawings, shown in FIG. 1 is a reproduction system or copier/duplicator 10 embodying the present invention. There shown is an upper frame assembly 20 pivotably supported by suitable means, for example, a shaft 535, on a lower frame 25. As an exemplary practice of the invention, a film stencil is thermally exposed to an original, and the stencil is used as a master in a mimeograph process to duplicate the desired number of reproductions. To receive an original and initiate machine operation, an original feed assembly 30 is provided. For feeding or paying out a desired length of stencil material in predetermined relationship to the original feed, a stencil feeding and cutting assembly 31 is provided. Infra-red or thermal exposure of the stencil to the original is made at an imaging station 32. A path 34 is provided for carrying the sandwich of original and exposed stencil to a transfer station 35, herein shown as a pneumatic transfer system, for separating or stripping the original from the stencil, and transferring the stencil to a mimeograph printing form, exemplarily shown as a cylinder 36, while directing the original to a receiving tray 38. As exemplarily shown, the mimeograph cylinder is provided with a pneumatic clamp 39 selectively operable, either to provide an air intake to draw or grasp one end of a stencil and bring it to the cylinder and initiate laying of the stencil on to the cylinder, or to provide an exhaust to release or disengage an end of a used stencil and direct it into a stencil eject or take-up assembly 40. In a preferred practice of the present invention using the mimeographic duplication process, there normally is a reservoir of ink in the mimeograph cylinder which can seep through a pad positioned about the cylinder periphery. To keep the ink from drying in the ink pad while not being used, a used stencil is left on the cylinder oriented so as to overlay the ink pad while the machine is not being operated and sitting at rest. The first response of the machine to insertion of an original into the original feed assembly 30 is actuation of a feeder switch 41 which initiates an eject cycle in which the old stencil, clinging to the mimeograph cylinder, is removed and sandwiched between turns or layers of cap-

tive material, in the present instance a blotter web 43 wrapped in a roll 42. The blotter web 43 is paid out or supplied from a roll 44.

Thereafter, as explained, the stencil and original are fed out and thermally exposed as a sandwich to image the stencil, then the original is separated, and the stencil is transferred to the mimeograph cylinder by the structure referred to above.

Reproductions are made by feeding, to the left as viewed in FIG. 1, individual sheets 45 from a stack 46 using a standard paper feeding system 48. Each sheet passes into the crotch between the mimeograph cylinder 36 and an impression roller 49 where ink is impressed through the stencil onto the copy sheet. The copies, duplicates or reproductions are stacked on a tray 50.

ORIGINAL FEED ASSEMBLY

Turning to FIGS. 2, 3A, 3B, and 4, thereshown is an exemplary structure for receiving and feeding an original into the system 10. As shown in FIG. 2, a chute for receiving an original 59 to be copied is defined by a lower plate 60 and an upper plate 61. The latter directs the original to a roller pair assembly 62 including a lower capstan roller 64 and an upper roller 65. As best shown in FIG. 3A, the rollers are not continuous but are sectional with the sectional portions of the lower roller mounted on a shaft 66 and the complementary sections of the upper roller mounted on a shaft 68. The lower shaft 66 is journaled in a pair of machine upper frame members 69, 70, defining the main opposite support side walls of the upper part of the machine, while the upper roller shaft 68 is rotatably journaled in pivot arms 71, 72. As will be explained with reference to FIGS. 3B and 4, the upper roller sections are movable up and down with respect to the lower roller sections 64. To define a chute for continuing to direct the sheet movement into the machine, another set of lower and upper plates 74, 75 are provided. The latter are provided with respective cut-outs 76, 78 to permit the roller sections 64 and 65 to extend through the chutes so that they may contact the original 59 and forward the latter during a predetermined period of machine operation.

To limit the movement of the original at a predetermined location so that the machine eject cycle can be initiated before the original and stencil are fed out and sandwiched together, in the exemplary embodiment a set of spring biased stop fingers 79 are provided. The upwardly extending stop fingers 79 may be formed in a longitudinally extending strip 80 which is connected by suitable means to bell crank arm 81 on one side and a bell crank arm 82 on the opposite side. Both arm 81, and bell crank 82 are pivotally carried on the lower roller shaft 66. Bell crank arms 81 and 82 are biased counter-clockwise as viewed in FIG. 4 by a pair of respective springs on opposite sides of the machine, one spring 83 being shown. As is explained later, bell cranks 82 and 83 carry respective pins, one of which 84 is shown, actuatable to selectively move the stop fingers 79 either downwardly, so as to not engage and thereby release the original permitting it to be forwarded, or upwardly and thereby blocking forward movement of the original.

For selectively bringing the upper roller 65 down against the original positioned between rollers 64 and 65, and also to lower the fingers 79, an actuating as-

sembly 85 is provided (see FIGS. 3B and 4). As exemplarily shown, the latter includes a solenoid 86 connected by linkages 88, 89 and pins 90, 91 to a hub 92, for example by a brazed connection between the latter and arm 89, and the hub 92 is fastened to a rocker shaft 94. The rocker shaft 94 is journaled at its opposite ends in respective frame members 69, 70. The arms 71, 72 are suitably mounted to pivot with the rocker shaft 94. As herein exemplarily shown, the arms 71, 72 are riveted or brazed onto respective annular connectors or hubs 95, 96 which are pinned to pivot with the rocker shaft 94.

As can be observed from FIG. 4, actuation of the solenoid 86 effects counter-clockwise rotation of rocker shaft 94 and effects a downwardly swinging movement of arms 71, 72 bringing the roller 65 down toward lower roller 64. At the same time integral depending lugs, one on each side of the machine, only one lug 98 being shown, are carried by the arms 71, 72 and engage actuating pins 84 carried by bell cranks 81, 82 and pivot the latter around the support shaft 66 against the bias of the springs 83 so as to lower the stop fingers 79. De-energization of the solenoid 86 allows the springs 83 to act so as to pivot bell cranks 81, 82 counter-clockwise and return the stop fingers into position to prevent an original sheet from moving beyond the stop position and also raising the upper roller 65 to permit an original sheet to be inserted into the chute between plates 74, 75.

To direct the original along a predetermined path after the stop fingers are lowered, a set of confining lower and upper wire forms 100, 101 are provided. In the exemplary embodiment the paper is driven along the aforementioned path by effecting rotation of the lower capstan rollers 64 with forwarding rollers 65. As will be described in relation to the overall drive system, a sprocket 102 for receiving a chain 104 is suitably fastened to the shaft 66, for example, by a set screw 103.

In the illustrative embodiment the original and master are fed through the machine so as to have a predetermined relationship with the end of the master being ahead of the original, or if a carrier is used for the original, ahead of the carrier end. The purpose of this will be understood when the separating, transferring and loading assembly 35 is described. To this end, the speed of rotation of the lower capstan roller 64 and the length of travel along the path defined by wire forms 100, 101 must be in predetermined relationship to the length of travel and speed at which the master material is paid out. As will be explained, the printed portion of the original must be in predetermined registry with respect to the forward end of the master so that the printing imaged on the master is disposed in the reproduction region of the mimeograph printing form. Also, the master must lead the original so that pneumatic action is effected on the master when the original stencil sandwich is carried by the transfer assembly 35.

STENCIL FEED AND CUTTING ASSEMBLY

Turning now to FIGS. 2, 5 6A and 6B, the exemplary embodiment uses a material for making a mimeograph stencil a heat sensitive film material in roll form. Describing the stencil feeding and cutting assembly 31 in more detail, a roll of stencil material is suitably carried for free rotation on a shaft 106 supported by a pair of bifurcated blocks, one of which 108 is shown. A single layer 109 of stencil material is paid out from the outer

layer of the roll 105 (see FIGS. 2 and 6A) over a bed plate 110. For feeding the layer of stencil material 109 from roll 105, it is gripped in the nip between rollers 111, 112 comprising an integral part of respective shafts 114, 115. As shown in FIG. 5 which is a partial section viewing the machine along a line 5—5 to the left in FIG. 2, the shafts 114, 115 are rotatably journaled in opposite side frame members 69, 70 by use of suitable bushings, in the present instance, bushings 116, 117, 118, 119. The frame members 69, 70 are provided with enlarged openings 120, 121 for receiving the upper bushings 118, 119 so that a pair of biasing springs 122, 124 anchored in respective frame members 69, 70 can bias the roller 112 into engagement with roller 111. As shown in FIG. 5, the spring 120 is wrapped about floating bushing 118 and the spring 121 is wrapped about the other floating bushing 119. The bed plate 110 is provided with cut-outs 125 to permit the roller portions 111 to extend through the plate and engage the stencil layer 109. The exemplary embodiment utilized knurled surfaces on the lower rollers 111 and flexible smooth surfaces, for example rubber, on the upper roller 112. The latter aids in feeding of slick surfaced stencil material.

The roller shafts 114, 115 are positively coupled to facilitate forwarding of the stencil. As herein illustrated, the shafts 114, 115 carry respective gears 126, 128 keyed by pins 126a, 128a to the respective shafts. The lower shaft 114 is the driven shaft. For applying drive to the latter, in the present instance, a drive sprocket 129 is rotatably journaled on a reduced diameter end 114a of shaft 114 and adapted to selectively apply drive thereto through an electric clutch 130. The latter includes a face plate drive member 131 and an annular driven member 132. The driven member 132 includes a stationary selectively energizable coil 134 surrounding and mounted for relative rotation about a hub part 135 of the annular member 132. The coil 134 is kept from rotating by an assembly including a stand-off pin 134a carrying a slotted finger 134b biased against the coil 134. The hub part is connected by suitable means, for example, a set screw 136 to the shaft 114a. Drive is transmitted to the sprocket 129 by the afore-mentioned original drive chain 104. Accordingly, the original and stencil can be driven in step. The sprocket free-wheels on the shaft 114 until the clutch coil 134 is energized, then drive is transmitted to the shaft 114.

For selectively cutting the correct length sheets of stencil material a knife assembly 139 is provided. As herein illustrated, the knife assembly includes a rotary cutting member 140 and biased strike member 141. The knife assembly 139 is of the well-known helic cut rotary knife form which is used in other A. B. Dick machines, for example, for cutting across a sheet of paper. The knife structure has the advantage that it reduces the area of paper which is under pressure by the knife at the cutting edge so as to reduce resistance and facilitate the cutting action. The rotary member 140 is turned or torqued by a rotary solenoid 142 located at the end of rotary member 140 away from the viewer as shown in FIG. 6A. As shown in the enlarged section of FIG. 6B, the rotary solenoid includes a plunger 143a suitably coupled to one end of the knife blade 140 by a sleeve union assembly 143b so that when an electrical coil 143c is energized a plunger plate 143d is drawn against balls 143e, and because of the inclined path of

5 a set of ball engaging tracks 143f the linear motion is transposed into a twist action. A hairspring 143g applies a rotary biasing force to the knife blade 140 to normally maintain it in a start position. The coil 143c is energized at the correct point in time to cut a desired length of stencil material.

10 Because the exemplary stencil material has a tendency to curl after an edge is cut, as a feature of the present invention, a hold-down assembly 144 is provided. As herein illustrated, the hold-down assembly operates as a kind of flutter valve and includes a flap 145 suitably connected to a tie bracket 146, in the present instance, by a plurality of spaced apart screws 148, and the bracket 146 is mounted on the arms 71, 72. The flap 145 extends between the nip defined by rollers 111, 112, cut-outs being provided so that the rollers 111, 112 can engage the layer of stencil material, and the flap 145 overlays the stencil material extending into the knife zone. To provide additional hold-down action 15 a bail 149 is supported on frame members 69, 70 by pins 150, 151 so as to ride on a flap forward edge 145a and apply a light hold-down force, assuring that the flap lies against the stencil web. Accordingly, the flap edge 145a rests right up against the edge of striker blade 141 so that after the stencil layer is cut by the rotary knife blade 140, the stencil is not permitted to curl back upon itself to an extent that would interfere with forward travel of the stencil past the rotary knife blade 140.

20 30 It is, of course, the trailing edge of a stencil sheet that is cut by the knife assembly 139. The illustrative embodiment of the machine uses a predetermined length of stencil material, in one practical instance approximately 14 inches in length, adapted for use for a particular diameter mimeograph cylinder. Of course, different size mimeograph cylinders may utilize different lengths of stencil materials. As is explained subsequently, controls effect operation of the stencil feed rollers 111, 112 for a predetermined period of time to feed out the desired length of stencil material. The stencil web is fed past the rotary knife 140 and on to a transport belt assembly 151 (see FIGS. 2, 7A, 7B, and 7C). To improve tracking, instead of using a single belt having a width equal to that of the stencil material, a plurality of belts are provided across the width of the machine. An exemplary portion of the belt assembly 151 is shown in FIG. 7B including individual belts 152 which are individually carried on respective idler roller segments 154 formed on a common shaft 155 so as to be positioned transversely of stencil travel and a set of complementary drive roller segments 156 formed along another common shaft 158. FIG. 7C shows how a single belt 152 is trained about the rollers. Interposed between the roller portions 154, 156 are longitudinally extending spacer bars 159, received in annular grooves 161, 162, respectively, formed by spacing the larger diameter roller segments 154, 156 along the axes of shafts 155, 158, respectively. The spacer bars 160 are held in position by a pair of transverse rods 164, 165. Of course, the bars 160 can be formed so as to snap into position and not require the afore-mentioned rods. 35 40 45 50 55 60 65

For driving the shaft 158, a sprocket 166 is mounted thereon and engaged by the drive chain 104. It will be recalled that drive chain 104 also drives the original feed and the stencil feed assemblies so that the drive of belt assembly 151 is in step with the feeding of the original and stencil.

For directing the stencil along a path overlying the belt assembly 151 a cover wire form 168 is provided. The stencil is directed toward a junction 167 (see FIG. 2) with the original at the end of the chute defined by respective wire forms 100, 101. Junction 167 is also the entrance into the thermal imaging or heat exposure station 32.

IMAGING ASSEMBLY

Turning to FIGS. 2, 7A, and 8A, as thereshown, the original and stencil are sandwiched together on entering the thermal imaging station 32 and then exposed to an infra-red heat source 168. The latter is supported within a rotatable insulating glass tube 169. The tube 169 is supported by a pair of rollers 170, 171 being pressed against the latter by an endless belt assembly 172. The belt assembly 172 includes an endless belt 174 having a width substantially greater than that of the stencil and original sandwich to facilitate feeding. Preferably the belt is constructed so as to have layers of material, including an outer cloth layer, to give particularly advantageous results in thermal imaging. The latter is described in detail in my co-pending U.S. Pat. application, Ser. No. 71,619 referred to earlier. The belt 174 is reverse wrapped about a portion of the glass insulator tube 169 and also trained about three rollers 175, 176 and 178. These rollers have their ends rotatably journaled in respective cradle brackets 179, 180 (see FIG. 8A).

As can be seen in FIG. 7A, the glass tube 169 is held captive between rollers 170, 171 and the belt 174. For effecting rotation of the tube 169, the roller 171 has a sprocket 181 associated with it which is driven by a thermal imaging drive chain 182. For applying drive to the belt 174 the roller 175 has a drive sprocket 184 associated with it. The sprocket 184 is also powered by the chain 182. The glass tube 169 and the belt 174 are driven in step so that there is substantially little sliding movement between the original and stencil as it is exposed to the heat source 168. Additional details may be obtained as to the construction and operation of the thermal imaging assembly 32 by referring to co-pending Bach U.S. Application Ser. No. 878,049 referred to previously. In a well-known manner, the characters on the original form heat sinks which create localized areas of high heat intensity at the stencil of the shape of the characters. In the mimeograph process these character areas thermal imaged on the stencil will permit the ink form the mimeograph pad to pass through and be applied on the medium used for making reproductions.

In one practical embodiment of the present invention, travel of the original and stencil sandwich has been found to be facilitated by use of a plurality of teflon strips, exemplary ones being identified by the reference character 185 in FIGS. 7A and 8A. At the upper end these strips are commonly connected to a strut 186 which is suitably supported (not shown) by the machine frame. The strips 185 follow the contour of the belt 174 about the glass tube 169 and then pass through an opening in a path defining chute 188. The latter is provided with a longitudinal slot 189, as best shown in FIGS. 7A and 8A to permit the original and stencil sandwich to travel from the exposing or thermal imaging station 32 to the separating, transferring and loading station 35. The chute 188 includes a pair of converging longitudinally extending legs 190, 191 adapted

to direct the sandwich to the slot 189. The leg 190, in the present instance, includes a lip 192 adapted to contact the glass tube 169. In one practical instance the lip was made of teflon. The chute 188 includes a generally transversely extending arm 194 which is pivotally supported on a pin 195. The latter is suitably carried by the machine frame. The arm 194 has an end connected to a spring 196 which acts to bias the lip 192 against the glass tube 169 so as to assure that if the stencil sticks to the latter, it is stripped off. The strips 185 are supported at their lower end by individual springs, one spring 198 being exemplarily shown. The strips 185 assure that the sandwich of the original and stencil do not follow the belt 174 after the exposure of the stencil. 15 The springs 198 are mounted on a transversely extending rod 199.

SEPARATING, TRANSFERRING AND LOADING ASSEMBLY

20 Turning to FIGS. 8A, 8B and 9, thereshown is an exemplary embodiment for effecting automatic and reliable separation or stripping of the original and the master without damaging the original and also effecting a transfer of the master from the imaging station 32 to the mimeograph printing form 36. In the present instance, a pneumatic assembly is provided. The assembly 35 includes a valving system for attracting and carrying the master material and then releasing it to separate it from the original and permit the master to be loaded onto the mimeograph cylinder 36, while the original is stripped and transported to a tray 38. As exemplarily shown the valving system includes a cylinder assembly 202. The latter includes an outer cylinder 204 provided with rings of apertures 205 at longitudinally spaced intervals along the length of the cylinder 204. To form an enclosure for directing the pneumatic force through the circumferential apertures 205, the ends of the cylinder 204 are closed by a pair of opposite end pieces 206, 208. As exemplarily shown, the end pieces 35 may be fastened to cylinder 204 by set screws 209, only the structure for attaching end piece 208 being representatively shown. Each of the end pieces, 206 and 208 respectively, are provided with shaft portions 210, 211 respectively. The shafts are rotatably carried in opposite end bushings 212, 214 supported on machine frame members 69, 70 respectively. The shaft portion 210 is drivingly coupled to a sprocket 215 adapted to receive drive from the thermal imaging drive chain 182.

50 For controlling the pneumatic force transmitted through apertures 205, enclosed within cylinder 204 is a smaller diameter valving cylinder 216. The latter is mounted for relative rotation with respect to the outer cylinder 204 and is adapted to close apertures 205, except in circumferential portions where arcuate complementary slots 218 register with the aperture 205. Thus, as air flows into apertures 205 the original stencil sandwich is held against the outer cylinder by the air flow into the cylinder. Pneumatic action is mainly on the original which is the portion of the sandwich contiguous with the outer cylinder 204 and only a lead edge 109a of the master is acted upon.

55 To form an independent unit adapted either to remain in set position or to rotate within the cylinder 204, the valving cylinder 216 is provided with opposite end pieces 219, 220 held together by a pair of longitudinally extending screws 221, 222. The end pieces 219,

220 are supported on a central tubular shaft 224. The latter is journaled in an aperture 225 for rotation at one end. The aperture 225 is formed in the outer cylinder end piece 206, and rotatably supported at the opposite end within the hollow outer cylinder end shaft 211. Accordingly, the inner cylinder 216 may either be rotated with the outer cylinder 204 or held against rotation with the outer cylinder 204 turns. As is explained subsequently, the foregoing ability provides the desired valving action.

For controlling the inner cylinder 216 with respect to rotation of the outer cylinder 204, a single revolution spring clutch assembly 226 is provided. The clutch 226 includes a spring 228 wrapped about an end of outer cylinder end shaft 211 and a coupling collar 229 which abuts the end of shaft 211. The coupling collar 229 is attached to the tubular, inner cylinder drive shaft 224, in the present instance being formed as a yoke having an upper portion 230a and lower portion 230b which can be selectively drawn together by tightening of a pair of screws 231 (see FIG. 7A). A lug 228a of the spring 228 is anchored in the yoke portion 230a. Surrounding the spring is a barrel 232 supported on an annular end hub 211a carried by shaft 211, the hub 211a being anchored thereto by a set screw 211b. The barrel 232 has an aperture 234 for receiving a tang 235 projecting from one end of spring 228. The barrel 232 is normally held against rotation by a depending finger 236 adapted to be selectively dropped into an aperture 238 provided in the barrel. The finger 236 is an integral part of a bracket 237 which is pivotally supported on a pin 239. A solenoid 240, connected to an opposite end 237a of the bracket 237, is adapted to pivot the bracket about the pin 239 to selectively lift the finger 236 to disengage or engage, respectively, with the barrel 232. A spring 237b (See FIG. 7A) is also coupled to bracket 237 and is adapted to normally bias the finger 236 toward the barrel 232, in other words in the direction opposite to the action of solenoid 240.

If the finger is engaged with the barrel, then when the outer cylinder end shaft 211 rotates and frictionally tires to carry the spring 228 with it, the barrel holds the spring against rotation, thereby uncoiling and loosening the spring. However, if the finger is raised and the barrel is released, then the frictional engagement between the hollow shaft 211 and the spring 228 will carry the spring with the shaft and cause the spring to wrap about and grip the shaft end 211 and transmit drive to the coupling collar 229 through yoke portion 230a. As a result, drive is transmitted to the inner tubular shaft 224. Thus, in the latter instance, the inner cylinder 216 will rotate with the outer cylinder 204. Upon deactivation of the solenoid, spring 243 returns the finger 236 against the barrel 232, and when the finger drops into aperture 238 the barrel 232 is held against rotation. Accordingly, drive from hollow shaft 211 is disconnected and the inner cylinder 216 remains stationary while the outer cylinder 204 rotates.

For permitting coupling of the source of pneumatic power to the transfer cylinder assembly 202 while rotation is occurring, a rotary pneumatic connection 241 is provided. The latter is similar to the pneumatic connection shown in complete assembly in FIG. 22. The pneumatic line extends through the hollow shaft 224 and communicates with the inner cylinder 216 through openings 242 provided at spaced locations along the length of the hollow shaft 224. The inner hollow cylin-

der permits air to be drawn through the outer cylinder 204 over a predetermined peripheral segment or arc 218a as defined by the slots 218 of the inner cylinder 216. In the exemplary embodiment, as can be best observed in FIGS. 8B, 24A, 24B and 24C, the region of attractive force acting on the original and stencil sandwich includes a segmental zone of about 127°. Once the stencil lead edge 109a is carried past the end of slots 218 and out of the attractive zone (See FIG. 24B), the stencil end falls away and is free for pick-up by the stencil holding assembly 39 of cylinder 36. Of course, when the inner cylinder 216 is rotating the segmental zone of attractive force also rotates and that is the manner in which the original is carried around and stripped from the stencil after the stencil end is grasped by assembly 39. In one practical instance the clutch 226 was timed to operate after the inner sheet or original had moved into a position substantially overlying the segmental zone 218a. Thus, the pneumatic force is substantially blocked from acting on the outer sheet, i.e. the stencil, to allow the sheet to be taken away from the transfer assembly.

For separating the original from the transfer assembly 201 and directing it to a tray 38, a stripper roller 243 along with a depending stripper finger 244 are provided. The stripper roller 243 is provided with cylindrical, spaced roller portions 245a carried by a shaft 245b and rotatably supported at the opposite ends in bushings 246, 248 carried by the machine frame members 69, 70.

STENCIL HOLDING AND RELEASING MECHANISM

It is another of the features of the present invention of providing an improved pneumatic system for selectively holding or releasing a master. Turning to FIGS. 2, 10, 11, 12A and 12B, thereshown is a master receiving and holding assembly 39 for an exemplary printing form. The exemplary master holding and releasing assembly provides both a pneumatic force for drawing and grasping a master, as well as a mechanical force permitting easy mounting of an ink pad over the cylinder diaphragm. Turning to an exemplary clamp 250, the latter is adapted for mounting on the mimeograph cylinder 36. To that end, the clamp is provided with opposite side brackets, one of which 251 is shown, attached to the clamp by screws 251a, 251b. A pair of cylinder side reinforcing plates 252a, 252b are provided to pivotally carry the clamp brackets. In that regard the brackets are provided with pivot pins, one of which 253 is shown, for mounting in the fixed plates 252a, 252b (See FIGS. 2 and 10). To provide respective clamp open and clamp closed positions the brackets are provided with lobe portions, a lobe 251c for bracket 251 being shown. Acting against the lobe 251c is a stud 254a carried on an arm 254b, which itself is pivotally supported on a pin 254c. A torsion spring 255 is also mounted on pin 254c and includes respective legs sprung away from each other, a leg 255a held by a pin 255b mounted on a fixed plate and a movable leg 255c acting against the arm 254b to press the stud 254a against lobe 251c. As is shown in FIG. 2, the clamp 250 may be pivoted open, or it may be snapped into a locked position.

As shown in FIGS. 2, 10 and 11 the clamp 250 has a radial surface generally following the contour of the mimeograph cylinder printing surface 258, however

the center is offset from the mimeograph cylinder center so that the clamp 250 is tilted downwards away from the mimeograph cylinder surface and into the cylinder void. The reason, as will be understood by those skilled in the art, is to prevent impression cylinder bounce by hitting the clamp edge. The clamp 250 is located at a circumferential end of the printing surface 258 which includes an ink absorbent outer pad 259 over an inner ink metering screen or diaphragm 260. The pad is conveniently removed or installed by opening and closing the clamp 250 as described above. As will be understood by those skilled in the art, there is a tail clamp also, to hold down the other end of the ink pad. Ink is placed inside the cylinder through an ink access assmbly 260a.

Describing the pneumatic features of the clamp 250, referring to FIGS. 10 and 11, a lead end 109a of the stencil web 109 is pneumatically grasped and held in the exemplary embodiment, by a series of three rows of apertures 261, 262 and 263 which communicate with a common chamber 265. When air flow is drawn or directed into the chamber 265 through the rows of apertures, the stencil forward end 109a or pulled against the clamp 250. The row of apertures 261 are provided with a longitudinal slot 266 and the clamp 250 is formed with a recess 268 so that the slot is actually located below the peripheral outline of the clamp 250 thereby providing space for the lead end of the stencil to mechanically fold into the slot 266 and facilitate holding of the stencil. Furthermore, the slot mechanically retains the stencil when the air supply is turned off, thereby assuring that when the eject cycle is initiated with air blowing out of the clamp, the stencil is snugly against the clamp. Thus, it can be understood how a drawing force or grasping zone can be established by the flow of air into chamber 265 to bring the stencil end against the clamp 250. After the end of the stencil is engaged with the clamp 250 and held there by the action of apertures 261, 262 and 263, continued rotation of the mimeograph cylinder 36 in a counter-clockwise direction as shown in FIG. 10 and clockwise as shown in FIGS. 24A-24C, lays the stencil over the ink pad 259. The ink on the pad will cause the stencil to cling to the pad.

On the other hand, if it is desired to eject the stencil, then directing air into the chamber 265 will force air out the apertures 261, 262, and 263 and blow a portion of the stencil away from the surface of clamp 250, thereby releasing or discharging the stencil end and permitting it to be caught by the used stencil take-up assembly 40.

Describing the system for selectively drawing air into, or forcing air out of the chamber 265, a conduit 269 is coupled to a connector 270 communicating with chamber 265. The conduit 269 is formed so as to extend laterally toward a side wall 36a of the mimeograph cylinder and through an aperture 271 formed therein.

To understand how pneumatic power is directed to the conduit 269, reference should be made to FIGS. 22, 23. A rotary pneumatic coupler 272 is provided at an outboard end of a mimeograph drive shaft 274. The latter includes a central passageway 274a and is drivingly connected to the mimeograph cylinder side wall 36a by a drive hub 275. Adjacent the mimeograph cylinder sidewall 36a, the drive shaft 274 is provided with an opening 276 to permit communication with the central passageway 274a. The conduit 269 is formed with a

generally U-shaped coupling end 278 for connection with the opening 276 to receive pneumatic power coupled into the drive shaft central passageway 274a.

An exemplary pneumatic system for selectively drawing air inwardly through the apertures 261, 262 and 263, or forcing air out through the latter is shown in FIGS. 12A, 12B. The conduits are diagrammatically shown. A spool valve assembly 280 is selectively operable to control air flow at the apertures 261, 262 and 263. A vacuum pump 281 powered by a motor 281a is connected to the spool valve assembly 280. For details reference can be made to Gallagher U.S. Pat. No. 3,469,526 assigned to A. B. Dick Company, the assignee of the present application. The spool valve 280 includes a cylinder 282 having six ports 284, 285, 286, 287, 288 and 289. Within the cylinder or barrel 282 a spool or piston 290 is slidably supported and adapted to be actuated by a solenoid 287. The spool or piston, in the exemplary embodiment, is spring biased so that upon energization of the solenoid 287 the piston is actuated to the position represented in FIG. 12A, while being normally held in the position represented in FIG. 12B. The piston 290 fits snugly within the cylinder 282 and is provided with a pair of ducts 291, 292 adapted to permit communication between a pair of ports extending longitudinally along the side of the barrel 282. To force air through the apertures 261-263 the spool valve is positioned so as to permit communication between ports 284, 285 in the barrel 282 and communication between another set of ports 288, 289 in the side of the barrel 282, spaced circumferentially from ports 284, 285. In the exemplary embodiment, a filter 294 is provided in passageway 284 so that when air is drawn from the atmosphere by vacuum pump 281 through duct 292 and port 285 and pipe 295, dirt particles are prevented from entering the system. Connected to the exit end of the pump 281 is a tube 296 which is in communication with port 288 and through duct 291 to port 289 and another conduct 298. The latter is coupled to a T connection 299 which has its other two openings coupled with spool valve port 286 and, through suitable conduits not shown, to the clamp connecting conduit 269, respectively. As is represented by the arrows in FIG. 12A, spool valve 280 is operative to direct or force air out of the apertures 261-263 and blow away or release the stencil end which was held by the clamp 250.

Turning to FIG. 12B the spool or piston 290 is shown moved to the left so as to use the ducts 291, 292 to effect communication between ports 285 and 286 on the side of the barrel 282, and ports 287, 288 on another, circumferentially spaced apart portion of the barrel 282. As a result, operation of pneumatic pump 281 will draw air through the conduit 269 and T 299, the conduit 298 being plugged by the new position of the spool 290; and through ports 286, duct 292 and port 288 and pipe 295 to the pump 281. Air is expended from the pump 281 through pipe 296 and ports 288, duct 291 and port 287. In the present instance, the normal position of the spool valve is as shown in FIG. 12B with air being drawn inwardly through apertures 261-263 to grasp the stencil end. Thus, unless the solenoid 287 is energized the clamp 250 is operative to draw or grasp a stencil end.

USED STENCIL TAKE-UP ASSEMBLY

It is another feature of the present invention that an

improved sheet storing system is provided for automatically receiving and storing a sheet carried on the printing forms. In the exemplary embodiment, the stencil take-up assembly 40 is adapted to receive and store a used, ink contaminated mimeograph stencil without manual aid. Turning to FIGS. 13-16 and particularly FIGS. 15 and 16, the take-up assembly 40 includes a sub-frame or cradle 301 having a pair of opposite side plates 302, 303 and tie bars 304, 305 and 306. The cradle is carried by a pair of lower machine main frame members 69a, 70a positioned on opposite sides of the machine below corresponding frame members 69, 70 of the upper part of the machine. Spanning between frame members 69a, 70a are tie bars 308, 309 and 310. The cradle 301 is pivotably supported on a through-shaft 311 which itself extends through and is rotatably journaled in the frame members 69a, 70a.

For selectively locking the cradle 301 in either an operative position or a loading position, the cradle plates 302, 303 are provided with ears 314, 315 and 316, 317, respectively (see FIGS. 13, 15 and 16). These ears are provided with keyhole shaped apertures 314a, 315a and 316a, 317a, respectively, for receiving a common, spring biased rod 318. The latter has a first, larger diameter portion 318a normally biased by a spring 318b into engagement with the body or larger cross-sectional portion of the keyhole slots 314a-317a so as to hold the cradle 301. The rod 318 also has necked-down portions 318c adapted to slip through the smaller cross-sectional portions of the keyhole slots 314a-317a so as to release the cradle for pivotal movement. The cradle is released by pushing inwardly on rod end 318d. The necked down portions 318c associated with the opposite ends of the rod 318 are located so that upon being pushed sufficiently inward, they simultaneously align with the keyhole slot reduced diameter portions to release the cradle. When released, the cradle 301 can be swung, for example, clockwise as viewed in FIG. 15, and the keyhole slot body portions 314a, 316a engaged with pin portions 318a to hold the cradle in a loading position. The web supply roll 44 and the used stencil take-up roll 42 can then be replaced. After loading the rod 318 can again be actuated to release the cradle so that it can be returned counter-clockwise, to engage keyhole body portions 315a, 317a with pin portions 318a to hold the cradle in an operative position.

For catching and captivating a sheet such as a discharged duplicating master, a web 43 is transported from the supply roll to the take-up roll, being trained so as to define a catching zone 323. Describing the web transport system in greater detail, the supply roll 44 is provided with stub shafts 320, 321 received in slots formed in the cradle side plates, one slot 322 in plate 303 being shown, which permit the supply roll to rotate as the web 43 is pulled. As exemplarily formed, the slots are inclined so that once the stub shafts 320, 321 are installed, the weight of the roll 44 keeps them in the slots.

To retard the paying out of web 43 from the roll 44 thus preventing overtravel from inertia of the web, a retarding flap 324 is spring biased against the periphery of the supply roll 44. The flap 324 is pivotably supported on tie bar 306. A torsion spring assembly 325 is carried by the bar 306 and has a fixed end 325a suitably connected to the stationary tie bar 306, and another end 325b flexing or acting against the flap 324.

The web 43 pays off the top of the roll as viewed in FIG. 15 and is received in a nip 327 between a pair of positive feed rollers 326, 328. The rollers 326, 328 are rotatably journaled in cradle side frames 302, 303. The upper roller 326 is provided with a drive sprocket 329 (see FIG. 14) outboard of the side frame 303, and inboard thereof carries a spur gear 330 which engages another spur gear 331 provided at the same end of the lower or capstan roller 328. The rollers and gears are biased into engagement so that the rotation of the rollers will draw the web 43 from the supply roll 44 through the nip 327. As can be best observed in FIGS. 13 and 15, the web 43 is trained about the lower roller 328 so that it leaves the roller on the same side that it enters the roller.

For taking up the web paid out from the positive feed rollers 326, 328 the take-up roll 42 is provided. The latter is supported on a torsion bar assembly 332 which includes a torsion shaft 334, in the present instance, hollow to permit the drive shaft 311 to extend therethrough, having integral outboard arms 335, 336. At each of the arm distal ends assemblies 338, 339, respectively, are provided for removably engaging the take-up roll 42. The end assembly 338 includes a drive sprocket 340 adapted to drivingly rotate the take-up roll 42. At the opposite end, the assembly 339 includes a spring biased release plunger 341 which in the present instance can be pulled out to disengage the take-up roll 42 and permit it to be removed from the cradle assembly 301. The torsion bar assembly 332 is swingable about the throughshaft 311 to carry the take-up 40 roll 42. For normally biasing the take-up roll 42 against the lower feed or capstan roller 328, a pair of bias springs 342, 344 couple the arms 335, 336 to adjacent cradle side members 302, 303 respectively. The capstan roller 328 acts as a gauge assuring that the wind-up or take-up roll 42 is always maintained a predetermined distance from the printing form regardless of the quantity of web material wrapped thereabout.

As can be observed in FIGS. 13 and 15, a used stencil is wrapped or captivated between layers of the web as the web is wound-up on the take-up roll 42. The web defines the catching zone 323 between the web 43 coming off the lower roller 328 and being laid onto the roll 42, and the outermost web layer, already wrapped onto the take-up roll. Accordingly, after a stencil end is disengaged from the cylinder clamp 250 and blown into the catching zone 323, as the mimeograph cylinder is rotated at eject speed the clinging stencil is pulled off the printing form surface 258. Drive is applied to the eject or take-up assembly 40 for a short period of time sufficient to wrap a used master between layers of the web on the wind-up roll 42. Accordingly, in the exemplary embodiment a storage zone is provided for the used master.

Describing the drive system, drive is received from a drive gear 350 coupled to the mimeograph cylinder 36. A driven gear 351 carried on a stub shaft 352 is in meshing engagement with the gear 350 and transmits power to a clutch 354. The latter may take the form of an electric clutch which by selective energization, as is described in detail subsequently, controls drive therethrough. A drive sprocket 355 is carried on a stub shaft 355a supported in frame 70a and adapted to receive drive from the clutch 354, transferring power through a chain 356 to a driven sprocket 358. The latter is located outboard of frame member 70a and keyed to the

through shaft 311 and applies rotative power thereto. Inboard of the frame member 70a, and also keyed to the shaft 311 is another drive sprocket 359. The latter transmits drive through a chain 360 to the sprocket 329 of the upper positive feed roll 326. On the opposite side of the machine another drive sprocket 361 is also keyed to the shaft 311 and by a chain 362 transmits drive to the supply roll drive sprocket 340. The sprocket 361 is coupled to the shaft 311 through an O-ring slip clutch in the hub 338, in one exemplary embodiment a Midwest Automatic In. SC 1 variable torque slip clutch was used, so that the supply roll is pulling the web faster than the feed rollers 326, 328 are paying it out. A slipping action occurs at the clutch to assure that the web is tightly wound or laid onto the take-up roll. Accordingly, the stencil is tightly held captive between layers of blotter paper.

CYLINDER ASSOCIATED TIMING AND CONTROL ASSEMBLY

As a further feature of the present invention timing mechanisms are provided for initiating eject speed movement of the printing form for disengaging a portion of a used master therefrom, for operating the eject or discharge assembly to catch and store the used master, for terminating eject speed operation, and then simultaneously starting master transfer to the printing form while controlling relative movement between the latter and the transfer assembly bringing them into predetermined proximate relationship, and also for controlling relative movement between the printing form clamp and the transfer station thereby providing a catching zone in which the master end is grasped and then laid onto the printing form.

Turning to FIGS. 17 through 26, therein are shown representative timing and control mechanisms for a printing form in the present instance associated with the mimeograph cylinder main drive shaft 274. The latter is provided with a splined end plate 274b for engaging internal splines provided in the hub 275. As explained, the latter is anchored to the mimeograph cylinder side wall 36a.

Turning first to the assembly for controlling the proximate relationship between the transfer station and the printing form and controlling movement for providing a master or stencil catching zone, as best shown in FIGS. 17 through 20, a latch and cam assembly 365 is provided operative to selectively raise and lower the upper frame 20. The purpose is to bring the master or stencil carrying transfer assembly 35 into close proximity to the printing form, herein shown as a mimeograph cylinder in preparation for providing a grasping zone for transferring the master or stencil to the printing form. Provided on each side of the upper frame assembly 20 are lifter assemblies, only one of which is shown in FIG 18. As thereshown, the upper frame 20 is provided with a tab 366 threaded to receive a stud 368. The stud 368, and with the latter the upper frame assembly 20, are supported on a block 369 carried by a cam follower 370. The latter is pivotably supported on a shaft 371 extending the width of the machine and being pivotably supported in the machine side frames 69a, 70a. An arm (not shown) is provided adjacent the side frame 69a for carrying the other side of the upper frame. To hold the cam follower 370 in a disengaged position a latch 372 is provided having an undercut 374 for dovetailing with a lip 375 carried by the cam fol-

lower 370. The lip 375 is provided with a vertical land portion 376 which swings upwardly when the latch 372 is pivoted to release the cam follower 370 thereby pushing aside the latch 372 so that the undercut 374 cannot operatively engage the lip 375 until the follower is returned to a normal, high position at a predetermined point in the rotation of the mimeograph cylinder.

The latch 372 is pivotably carried on another post 10 378 also carried by frame member 70a. The latch 372 is biased in a clockwise direction as viewed in FIGS. 17, 18 by a spring 379 having one end attached to a pin 380 carried by the latch 372 and the opposite end anchored in a lug 381 mounted on a spacer stud supported on the 15 frame 70a. For selectively pivoting the latch 372 away from the cam follower lip 376, a solenoid 384 is connected by a link 385 to the latch pin 380. Energization of the solenoid 384 will pivot the latch 372 counterclockwise against the force of biasing spring 379 and 20 disengage the undercut 374 and lip 375 so that the follower 370 can ride on a driver or cam 386.

As best shown in FIG. 22, the cam 386 is mounted on a hub 388 which is spline fitted with the mimeograph cylinder drive shaft 274. A bushing 389 is provided in 25 frame 70a for receiving the main drive shaft 274 internally, while the hub 388 is disposed externally thereof. An annular spline coupler 390 is fitted between the drive shaft 274 and the hub 388 so as to abut the bushing 389. The spline coupler 390 is keyed to the drive 30 shaft 274 by a key 390a, while the hub 388 is slip fitted so as to be relatively rotatable. Also carried by the hub 388 is a main drive sprocket 391 and another cam 392 which will be described subsequently. The hub 388 is provided with an integral annular portion 394 interposed between the cam 386 and the drive sprocket 391, and is further adapted to carry a spacer ring 395 interposed between the drive sprocket 391 and the other cam 392. The assembly of cams 386 and 392 and drive sprocket 391 is held together by a set of three 35 bolts, 396, 397 and 398 shown in FIGS. 21 and 22. The cam 386 is mounted in fixed position on hub 388, and the latter is mounted so as to permit a small amount of angular adjustment relative to the coupler 390 which, of course, is keyed to the mimeograph cylinder drive 40 shaft 274 and thereby to the mimeograph cylinder 36. Accordingly, the cam 386 can be adjusted to have a predetermined angular relationship to the cylinder clamp 250. Explaining, the bolt 398 permits the cams 386 and 392 to be selectively adjusted in angular relationship to the mimeograph cylinder 36 for reasons to 45 be explained subsequently. To that end, the coupler 390 is provided with trunnion ears 390b, 390c between which the head of screw 398 is held by set screws 390d, 390e. The latter are threadably received in the ears so 50 that turning of the set screws angularly adjusts the relative position of cams 386 and 392.

Turning now to FIGS. 17 and 18 and the description 55 of the operation of the frame lowering cam assembly 365, as thereshown the cam 386 is provided with a high portion 386a. In the exemplary embodiment, even in the follower latched position a follower wheel 370a is touched by the cam high portion once every cylinder revolution, which is the time when load is removed from latch 372 permitting easy release. When the latch 372 is operated to release the cam follower 370, the cam follower wheel 370a is permitted to ride down into a low portion 386b of the cam 386. As a result the

upper frame 20 and particularly the transfer cylinder assembly 202 is brought down toward the peripheral surface of the mimeograph cylinder 36. This is best shown in the stop motion diagrammatic representations of FIGS. 24A, 24B and 24C. The proximate relationship of the transfer cylinder assembly 202 and the mimeograph cylinder 36 when the cam follower wheel 378 rides down into the low portion 386b is represented in FIG. 24A. The surface of the cam 386 is generated to have a predetermined configuration. Thus, the cam follower wheel 378 riding on that surface, as the cam rotates with the mimeograph cylinder, moves the cam follower 370 up-and-down, so that the transfer cylinder assembly 202 generally follows the surface configuration of the mimeograph cylinder clamp. The position of the cam follower 370 when in its lowest position with follower wheel 378 engaging cam surface portion 386c is shown in phantom in FIG. 18. Accordingly, the lowest portion of the cam surface 386c is related to up-and-down movement of the transfer cylinder assembly 202 so that the latter is brought down into the mimeograph cylinder void 36b (see FIG. 17) just missing the tail clamp section of the cylinder, in preparation for meeting the head clamp 250. It subsequently rises following the clamp contour. As will be understood from the description of the mechanism for controlling relative movement between the printing form clamp and the transfer station, the up-and-down movement of the transfer station is coordinated therewith so as to lay the stencil into a grasping zone 399. As shown in FIG. 24B, once the stencil end 109a is brought into the zone 399 it is grasped by the pneumatic clamp 250 of the mimeograph cylinder.

After the stencil end has been grasped by and drawn against the pneumatic clamp 250, it is desirable to raise the transfer cylinder assembly 202 up and away from the mimeograph cylinder periphery. To that end, the cam 386 is formed with a portion 386d which raises the assembly 202 out of the way.

The cam 386 continues to provide a dwell for the follower 370 via follower wheel 378 as the mimeograph cylinder 36 rotates so that the transfer assembly remains the same distance from the mimeograph cylinder as the master or stencil is laid down. When the cam returns to the original high portion, the cam 386a raises the follower 370 to its highest position so that the undercut 374 of the latch 372 engages the follower lip 375 to latch the follower 370, preventing it from following the cam 386. The position of the transfer cylinder assembly 202 as the stencil is laid on the mimeograph cylinder surface is shown in FIG. 24C.

As will be understood from an overall description of the operation of the copier/duplicator, the aforementioned cam 392, which is a positive stop cam, operates to provide a fine control over the rotation of the mimeograph cylinder after a used stencil has been ejected and a new stencil is in the process of being picked up. In the present instance, the control is effected by first holding the mimeograph cylinder in a ready position (see FIG. 24A) awaiting the arrival of the stencil end 109a in a grasping zone 399, and then releasing the cylinder so that the clamp 250 can be synchronously moved into position to grasp the stencil end and continue rotation without interruption, laying the stencil on the mimeograph cylinder periphery. To this end, a positive stop control assembly 401 including the cam 392 are provided. Describing the latter in detail,

a follower arm 402 is provided with a hub 382 having a bearing 382a for pivotably receiving a support to be described. Extending outboard from the follower arm 402 are a pair of follower rollers 404, 405 commonly carried on a pin 406, the latter extending through and being supported by the follower arm 402. A shoulder 403 is provided on pin 406 for fitting between the follower roller 405 and arm 402. Roller 405 engages a camming surface 408a on a latching lever 408.

10 The latter is pivotably carried on the mimeograph cylinder main drive shaft 274. The lever 408 is seated on an annular hub 409 which internally carries a bearing 409a for receiving, and permitting relative rotation with respect to the drive shaft 274. Another bearing hub 410 is carried by an outboard support plate 411 to rotatably receive and support the drive shaft 274. The support plate 411 is mounted on the frame side plate 70 using a plurality of spacer studs, one of which 412 is shown. The spacer stud also provides pivotal support 15 for the spring anchor 381 and the follower arm hub 382.

20 For maintaining the follower rollers 404, 405 biased toward the camming surfaces 408 associated with cam 392 and lever 408, a biasing spring 414 connects a distal end of the follower arm 404 with the machine frame 70a. Thus, the follower arm 404 is continually biased in a clockwise direction as viewed in FIGS. 17 and 21.

25 Describing the latching lever 408 in more detail, the latter is normally biased clockwise as viewed in the foregoing FIGS by a spring 415. The latter connects a lower end of the latching lever 408 as viewed in FIGS. 17 and 21 to the outboard side plate 411. The latch lever 408 may be selectively pivoted a limited angular amount by energization of a pair of solenoids 416, 418, solenoid 416 acting to pivot the lever counterclockwise and the solenoid 418 acting to pivot the lever clockwise. The solenoids are coupled to the lever 408 by a common link bar 419 and a latching lever pin 420. As best shown in FIG. 22, a stud 421 is provided between the lever 408 and the bar 419 to accommodate the offset position of the solenoid plungers. The solenoids are suitably mounted on the outboard side plate 411.

30 It is another of the several features of the present invention that a fail safe lockout is provided for the positive stop mechanism. Describing the exemplary structure in more detail, the follower roller 405 is normally positioned on a protuberance 422 of the lever 408. In that position the other follower roller 404 is held away from the surface of cam 392 so that it cannot follow the contour of the latter and engage a positive stop position to be described. As may be observed in FIG. 21 the spring 415 pivots the lever 408 so as to hold the protuberance 422 under roller 405, and the location and slope or rake of the protuberance 422 is such that the roller 405 acts on a negative rake angle against the lever 408. Accordingly, the greater the force applied by roller 405, the more reaction the lever 408 provides to maintain the roller 405 in a raised position. As explained, the spring 414 provides the force for maintaining roller 405 and protuberance 422 engaged.

35 40 After the used stencil has been ejected, during which the mimeograph cylinder has been rotating at an eject speed, the latching lever 408 is pivoted by energization of solenoid 416 thereby removing the support provided by protuberance 422 for the follower roller 405. Thus, the companion follower roller 404 is released to engage

the surface of cam 392. The release is timed to occur when a high or release portion 392a of the cam 392 is in position to engage the follower roller 404. At that time application of eject speed rotative power to the mimeograph cylinder 36 has been terminated. Accordingly, the mimeograph cylinder decelerates to thermal imaging speed at limited torque and the shape of the cam 392, as particularly denoted by reference character 392b, is such as to provide a particularly high cam pressure angle, approximately 90° in one practical instance, for engaging roller 404. Spring 414 acts to bias roller 404 in the cam pocket and limited torque is applied to the mimeograph cylinder holding the cam surface 392b against the roller. Thus, the mimeograph cylinder is held in a predetermined position, the clamp 250 positioned to one side of the transfer cylinder assembly 202 as generally shown in FIG. 24A. The frame lowering latch 372 is pivoted upon energization of solenoid 384 and allows the follower 370 to follow the cam 386. The positive stop cam 392 and frame lowering cam 386 are brought into predetermined relationship so that the respective followers, being released approximately simultaneously, engage the highs of their cams, thus preventing a jolting or clashing meeting of parts. When positive stop is reached the cylinder stops rotating, thus lowering of the transfer cylinder assembly 202 is also terminated and the control mechanisms await the transfer of the stencil end 109a past the influence of the segmental zone as defined by slots 218 in the inner valving cylinder 216. As generally shown in FIGS. 7A and 24A-24C the transfer cylinder assembly 202 is located to one side of the printing form 36 to direct the master 109 tangentially toward the clamp 250.

After the solenoid 416 has been energized to pivot lever 408 and release the follower roller 405, it is de-energized and the spring 415 acts to return the lever 408 into engagement with follower roller 405. Since the roller 405 has moved to a lower position another camming portion, a valley 424, of the lever 408 is brought into engagement with the roller 405. However, the action of spring 415 alone is not sufficient to raise the follower roller 405 and therewith follower roller 404 to release the latter from the positive stop engagement with cam pocket 392b. Thus the mimeograph cylinder is held in a known position ready for release at the correct time for moving into position to pick up the stencil end 109a. To release the mimeograph cylinder the release solenoid 418 is energized and the lever 408 is pivoted clockwise raising the follower arm 402 by causing the follower roller 404 to ride up on to the protuberance 422 of the lever 408. Thereafter the mimeograph cylinder is permitted to rotate at thermal imaging speed with full torque being applied, as will be explained subsequently, to move into position and pick up the stencil on the fly (See FIG. 24B). In summary, it will be appreciated from the foregoing description that the positive stop cam pocket 392b can be angularly positioned relative to the clamp 250 so that the positive stop release solenoid permits the clamp to move in and precisely meet the master or stencil end 109a.

One of the other features of the present invention is that a preparation cycle control is provided for preparing the reproduction system 10 to receive a new master. Thus, regardless of where the original is located, the positive stop control assures that the printing form clamp and master or stencil end are brought into proper registry. In the exemplary embodiment the

preparation cycle control is referenced to movement of the printing form 36. For providing electrical signals corresponding to predetermined angular positions of the mimeograph cylinder 36, and particularly the pneumatic clamp 250 thereof, a timing assembly 430 is provided (See FIGS. 25 and 26). In the exemplary embodiment a magnetic reference signal is provided. To that end a magnet 431 is mounted on a non-magnetic platform 432 carried by the mimeograph cylinder main drive gear 350 on a pair of pedestals 434, 435. In the present instance the pedestals are provided with screws 434a, 435a, respectively, to mount the platform 432. The magnet 431 is referenced with respect pneumatic the pneumatic clamp 250 and more specifically to the first row of apertures 261 and the coextensive stencil receiving slot 266. As shown in FIG. 25 in one exemplary embodiment, and angle α of approximately 25° is provided between the magnet 431 and the first row of apertures 261, the apertures being angularly advanced 20 of the magnet by that amount. Thus, the magnet 431 and responsive controls associated with it must provide signals to initiate machine operations involving the clamp 250, at least 25° before the magnet aligns with operational point.

25 To transmit the position signals as represented by the magnet 431 to the electrical system, in the present instance a set of reed switches 436, 438 and 439 are mounted on a common support plate 440 adjustably carried by a pair of pedestals 441, 442. The pedestals 30 are attached by a pair of screws 441a, 442a to the outboard side plate 411. Another pair of screws at the opposite end of the pedestals, screws 441b, 442b, hold the plate 440 in the desired position. The plate is provided with respective arcuate slots 444, 445 through which the screws 441b, 442b are received and upon loosening permit angular adjustment of the plate 440. The result 35 is that the reed switches 436 and 439 may be angularly positioned relative to the point where clamp 250 is brought into the stencil eject zone 323, and reed switch 438 may be angularly adjusted relative to the point where clamp 250 is brought into the stencil and catching zone 399. Thus, the impulses are initiated at precisely the right point to move the clamp 250 into position in the one instance, and coordinate arrival of the clamp 250 and the stencil and 109a in the other instance. Rotation in a counter-clockwise direction will advance the occurrence of the pulses and rotation in the clockwise direction will delay the occurrence of the pulses or signals. Two of the reed switches are provided 40 with independent adjustment with respect to the common support plate 440. Switch 438 is mounted on a bracket 446 which receives, in the exemplary embodiment, three screws 448, 449 and 450. The screw 448 extends through an arcuate slot 451 in the plate 440 and the screws 449, 450 extend through another arcuate slot 452 in the plate 440. In a similar manner the reed switch 439 is supported on a bracket 454 by three screws 455, 456 and 458 which are received in respective arcuate slots 459 and 460 in the plate 440. Thus, 45 besides the arcuate adjustment provided by the common plate 440, the reed switches 438, 439 can be independently adjusted; reed switch 438 relative to the desired cylinder positive stop position and reed switch 439 relative to reed switch 436 so as to provide precise timing signals. The use of the pulses provided by these reed switches will be understood with the explanation 50 of the control system of the copier/duplication which

is given in a subsequent portion of this description. As will be appreciated by those skilled in the art in viewing FIG. 26, the reed switches are also adjustable axially to assure that the magnetic field provided by magnet 431 couples properly with the armature in the reed switches to reliably operate them.

MASTER CAM COMPLEX

It is also a feature of the present invention that a function cycle control means is provided for effecting sequential operations to load the master on the printing form and go into the printing cycle. In the exemplary embodiment, because a master or stencil is imaged by the system, the function control effects operation of the original transport assembly, the stencil transport assembly, thermal imaging assembly, the frame lowering and raising driver, the positive stop assembly, the stencil and original separating and stencil transferring assembly, the stencil cut-off mechanism, the paper feed mechanism and print speed operation of the printing form.

In the present instance as shown in FIGS. 27 and 28, a master cam assembly 475 operates as a function cycle control providing a sequence of control signals to step the machine through predetermined cycles of operation responding to insertion of an original and stopping with initiation of the print cycle. In the present instance the master cam assembly 475 is mounted on an extension of machine main frame 70a. The master cam 475 generally has the configuration of a drum comprised of five spaced cam wheels, in the present instance, wheels 478, 479, 480, 481 and 482. For effecting rotation of the cam wheels, the latter are carried on a common hub 484 keyed to a shaft 485. As exemplarily shown, the cam wheels are sandwiched between a set of spacer rings 483a, 483b, 483c and 483d sandwiched together by a plurality of through bolts threadably received in an annular boss 484a integral with the hub 484, one of the bolts 486 being shown in FIG. 28. For rotating the shaft 485, a drive sprocket 488 is coupled through a single revolution spring clutch 487 of the same type as the already described clutch 226 shown in FIGS. 8A and 9. The sprocket 488 is fitted on a hub 489 which is mounted for relative rotation on a bearing 489a carried by the shaft 485. The shaft 485 is rotatably journaled in the frame 70a. Drive is transmitted to the sprocket 488 by a drive chain 490 which is driven by a sprocket 491 carried on a thermal imaging drive shaft 492. Describing the transmission of drive through the clutch 487, as noted, the sprocket 491 free wheels on the shaft 485, and is selectively coupled thereto. To that end a spring 487a has a portion wrapped about an end of the hub, that end of the spring being connected to a barrel 487b surrounding the spring. The other portion of the spring is wrapped about a collar 487c and has that end attached thereto. The collar is itself attached to the shaft 485, in the present instance by a set screw 487d, so that when the barrel 487 is released permitting a portion of the spring to wrap about hub 489, drive is transmitted from the sprocket driven hub to the shaft 485. For controlling rotation of barrel 487b and thereby operation of clutch 487, a finger 487e is selectively operated by a solenoid 487f. The finger is normally biased to hold the barrel 487b against rotation while a momentary energization of solenoid 487f disengages the finger from the barrel, and thereafter the bar-

rel is allowed to rotate for one revolution before the finger stops the barrel.

Associated with the cam wheels 478-482 is a set of signal producing means, in the present instance, nine microswitches M1, M2, M3, M4, M5, M8 and M9. The latter are adjustably supported in an arcuate array about the cam wheels on a pair of support plates 495 and 496. The profile orientation of the microswitches is indicated in FIG. 27. The plates 495, 496, best shown in FIG. 28, are carried on a pair of projecting ears 498, 499 which are integral with an outboard subframe 476. The latter is suitably mounted on, and outboard of the main lower frame member 70a by a set of stand-offs (not shown).

A representative showing is presented in FIG. 28 of the microswitches associated with the cam wheels 478, 479 and 480. It will be appreciated that the switches are particularly located, and the cam high portions are so oriented that the microswitches are actuated to give signals initiating respective machine operations in a predetermined sequence at preset time. The following table gives a complete correlation between the switches and the cam wheels:

25

Cam Table

	Cam Wheel	Operated Mechanisms	Micro-switch
478	Master Cam Clutch and Positive Stop Latch Positive Stop Latch Release		M1 M7
479	Stencil Feed Original Feed		M2 M3
480	Thermal Imaging Lamp		M4
481	Stencil Cutoff		M5
482	Stencil Transfer (Vacuum Cylinder) Print Speed Copy Paper Feed		M6 M8 M9

The microswitches are standard available components. In one practical instance Micro-Swtich Co.'s SM switches with JS-246 actuators were used. The operation and function of the microswitches will be explained in detail with reference to the electrical schematic in a subsequent part of this description.

DRIVE SYSTEM

Turning to FIGS. 29-32 and particularly FIG. 29, there shown is a schematic of the overall drive system for the copier/duplicator 10. Some of the components in the drive system have already been identified. The reference characters used previously are also used to identify corresponding machine components represented diagrammatically.

Describing the drive system beginning with the source of power, in the present invention, a motor 500, has an output pulley 501 which carries a V-belt 502 for driving another pulley 504 mounted on a main drive shaft 505. The latter is suitably mounted on the machine frame (not shown) for permitting rotation thereof. Power is taken off the main drive shaft 505 through mimeograph cylinder drive train 506 and a thermal speed drive train 508. An exemplary embodiment of the drive train 506 is shown in FIG. 30 and an exemplary embodiment of the drive train 508 is shown in FIGS. 31 and 32.

Describing the drive train 506 in more detail, the main drive shaft 505 includes a driving gear 509 in meshing engagement with a driven gear 510. The gear 510 is carried by and adapted to power an idler shaft

511, which itself is rotatably supported by a pair of bearing 512, 514 at the shaft opposite ends. The bearings are mounted in the machine frames. Spaced apart from the gear 510 is another smaller diameter gear 515 also mounted to rotate with the idler shaft 511. The respective gears 510 and 515 are of different diameter so as to provide drives of different speed to a speed selector 516. The speed selector includes a pair of gears 518, 519 carried on a shaft 520. The shaft 520 is journaled in bearings 521, 522 which are carried by the frame pieces 70a and 476. The respective gears 518, 519 are provided with hubs 526, 528 respectively which are rotatably mounted on the shaft 520 in predetermined axial position to hold the gears 518 and 519 in predetermined positions while allowing relative rotation between the gears and the shaft 520. Also carried by the shaft 520 is a mimeograph cylinder drive sprocket 529 which is suitably attached to the shaft 520 so as to be powered by the latter and to rotate with it. Another gear 530 is also carried by the shaft 520. However, the latter is mounted on an overrunning clutch 531 interposed between the gear 530 and the shaft 520. The overrunning clutch used in one practical instance was a Tarrington No. RC-061008 roller clutch and as installed on the shaft 520 it operated to allow transmission of drive in only one direction. That is, drive could not be transmitted out of shaft 520 through the gear 530, however, drive could be received by the gear 530 and applied to the shaft 520.

The drive sprocket 529 is connected to the mimeograph cylinder drive sprocket 391 through a chain 532. The gear 530 is in meshing engagement with a gear 534 mounted on a thermal imaging drive shaft 535 and adapted to rotate therewith. The master cam drive sprocket 491 is suitably keyed to an end of the shaft 535, in the present instance by tightening a set screw 491a. Also carried on the end of the shaft 535 inboard of the sprocket 491 is the electric clutch 494 for selectively applying drive to gear 534. The clutch 494 is described in detail subsequently.

Describing further the speed selector portion of the drive train 506, a clutch sleeve 536 is slideably carried on the shaft 520, being interposed between respective gear hubs 526, 528 and adapted to selectively transmit drive from either of these hubs to the shaft 520. To that end, the gear hub 526 is provided with a toothed face 538 adapted to mesh with a complementary clutch sleeve toothed face 539. In a like manner, the gear hub 528 is provided with a toothed face 540 adapted to engage a complementary toothed face 541 on the opposite side of clutch sleeve 536. As will be appreciated by those skilled in the art, the clutch sleeve 536 can be keyed to the shaft 520 so as to transmit drive thereto yet being axially slideable relative to the shaft. For effecting axial movement of the sleeve 536 the latter is provided with an annular groove 542 for receiving a shifter yoke 544 carried by a shifter lever 545. The shifter yoke 545 is pivotally carried on a pintle 546 supported by a brace 548 positioned transversely between frame members 524, 525.

Also pivotably carried on the brace 548 is a dog 549 supported by a pin 550. The dog 549 is provided with a seat 551 adapted to receive a roller 552 carried by the shifter lever 545. An end 549a of the dog 549 is connected to a spring 554, suitably mounted on frame member 525, so as to pivot the dog and urge the roller 552 into the seat 551. In this manner the shifter yoke

545 is normally held in a position so as to locate the clutch sleeve 536 in an axial position with both of its clutch faces 539, 541 disengaged from clutch driving faces 538 and 540, respectively. For pivoting the yoke 545 and thereby selectively engaging the clutch sleeve 536 with either gear 518 or 519, a pair of solenoids 555, 556 are provided. The latter are mounted on a platform 558 carried by the frame pieces 524, 525, and are positioned with their operating plungers facing each other so that they can pivot the lever 545 in opposing directions. A coupling bar 559 is attached to the shifting lever 545 by a pin 560. At its respective opposite ends the bar 559 is attached by a pin 561 to a plunger 555a and by a pin 562 to plunger 556a.

15 To apply eject speed to the sprocket 529, in the exemplary embodiment solenoid 556 is energized and lever 545 is pivoted clockwise bringing complementary faces 540 and 541 into engagement, face 541 comprising a part of clutch sleeve 536 and face 540 comprising a part of the gear hub 528. The result is that the shaft 520 turns at the same speed as gear 519 to drive the mimeograph cylinder 36 at eject speed, and also to drive the web of the eject assembly 40 at a predetermined speed. As shown in FIGS. 16 and 29 drive is transmitted from the sprocket 529 through the chain 532 to the mimeograph cylinder drive sprocket 391. The latter rotates shaft 274 to turn the main drive gear 350 which is meshed with a driven gear 351 to rotate a shaft 352. The shaft 352 is coupled through the clutch 354 in the present instance an electric clutch, to selectively drive the sprocket 355, the latter being rotatably carried on the shaft 352. The sprocket 355 transmits drive through the chain 356 to a driven sprocket 358 carried on the through-shaft or main eject speed drive shaft 311. The manner in which the various parts of the eject assembly 40 are driven has been explained previously, however, from the foregoing description it can be appreciated that the mimeograph cylinder 36 and the eject system 40 are driven in a coordinated manner so that the stencil is discharged into the catching zone where the web takes it up without tearing, and indeed in such a manner that it could be reused as a mimeograph master if desired.

40 45 To effect a faster print speed rotation of the mimeograph cylinder 36, the print solenoid 555 is energized. The latter pivots the shifter lever 545 counter-clockwise and causes the clutch sleeve face 539 to engage with the gear hub face 538 and thereby transmit drive from the gear 518 to the shaft 520. Because of the gear ratio between gears 510 and 518 this is a faster speed. Drive is thereby transmitted to the sprocket 529 which by way of drive chain 532 rotates the driven mimeograph sprocket 391. The eject drive clutch 354 is de-energized so that drive is not transmitted during the print cycle to the eject assembly 40.

45 50 55 As can be appreciated from FIG. 30, in the exemplary embodiment the dog seat 551 is shaped so that with energization of either solenoid 555 or 556 the shifter lever roller 552 is caused to ride up on to a portion above the lowest portion of the seat. The respective eject speed and print speed positions of the lever 545 and dog 549 are shown in phantom. Accordingly when the solenoids are de-energized the spring 554 pivots dog 549 so that roller 552 is returned to the lowest most point so that normally the clutch sleeve 536 stays in a neutral disengaged position.

Turning now to FIGS. 31 and 32 thereshown is the thermal imaging drive system 508 carried on an assembly plate 564. Describing the system, a drive pulley 565 is mounted on the shaft 505 to rotate therewith. The pulley 565 is of the well-known variable pitch type wherein a spring assembly 566 is provided on the hub so that when the tension on a belt is increased the sheaves of the pulley separate and change the drive diameter of the pulley. Trained about the pulley 565 is a V-belt 568 which couples the drive pulley 565 to an idler pulley 569 and a driven pulley 570. The driven pulley 570 is carried on a stub-shaft 571 supported in the assembly plate 564. Journaled to rotate with the driven pulley 570 is a drive gear 572. The latter is in meshing engagement with a driven gear 574 which is carried on another idler shaft 575. The latter is also journaled in the assembly plate 564. Mounted for rotation with the driven gear 574 is a drive sprocket 576 which is coupled by a drive chain 578 to a driven sprocket 479. The latter is mounted on and keyed to the main thermal imaging drive shaft 535. Inboard of the driven sprocket 579 is a drive sprocket 580 carried by the thermal imaging drive shaft 535 which is adapted to transmit drive through the thermal imaging drive chain 182 to the original and stencil feed drive, the thermal imaging belt, the thermal imaging tube and to the transfer assembly as has been described previously.

The shaft 535 carries power from one side of the copier/duplicator, the side generally defined by frame member 69, to the other side of the copier/duplicator, the side generally defined by frame member 70. Thus, by way of the driven gear 534 thermal imaging speed drive is brought to the drive selector 506.

Turning now to the electric clutch 494 and the drive gear 534 associated therewith, the latter can transmit drive to the gear 530 through the overrunning clutch 531 so as to rotate the shaft 520. However, if the shaft 520 is already being rotated faster than the speed that is being applied to the gear 530, then the gear 530 cannot transmit drive to the shaft 520. Thus, the gear 530 continually rotates at thermal imaging speed, and insures that the shaft 520 is rotating at thermal imaging speed as long as torque is being transmitted by clutch 494.

Describing the electric clutch 494 in greater detail, the latter includes a hub 581 suitably mounted for rotating with the thermal imaging shaft 535, for example, by tightening a set screw 582. The hub is provided with an integral annular portion 584 carrying a clutch driving face 585. Surrounding the hub 581 and positioned behind the annular portion 584 is a coil 586 which is selectively energizable to establish a magnetic field in the vicinity of face plate 585. The latter magnetic field acts on a driven clutch face plate 588 to couple it to the continuously rotating clutch face plate 585. The clutch face plate 588 is carried on an annular flange 589 which is mounted on a hub 590 coupling the driven clutch face 588 with the gear 534. The sleeve 590 is carried by a bushing 591 so that it is relatively rotatable with respect to the shaft 535. Thus, drive is applied by thermal imaging shaft 535 to the clutch face plate 583 through the hub 581. Indeed, this portion of the clutch 494 is continuously rotating at the thermal imaging speed. Drive is then selectively applied to the driven clutch face 588 and thereby to gear 534. By controlling the magnetic field which draws the clutch faces 585

and 588 together the amount of torque transmitted through the clutch can be selectively controlled. As has been explained, it is desirable to hold the mimeograph cylinder in a positive stop position while the stencil is being brought down toward the mimeograph cylinder for transfer thereto, and then immediately move the cylinder clamp in to pick-up the stencil on the fly. A slipping thermal imaging torque is applied to the mimeograph cylinder by the clutch 494, to hold it in the positive stop position, and also to immediately apply drive to the cylinder at thermal imaging speed when the positive stop is released. Explaining in one practical instance, about 50 per cent of the electrical power necessary for complete clutch coupling is applied to the coil 586. Thus, a selective torque is applied coupling the thermal imaging shaft 535 to drive the gear 534, yet allowing slip while the mimeograph cylinder is held in positive stop.

After the loaded stencil has been discharged, the shaft 520 is stationary or coasting down. Under these circumstances the gear 534 is rotating faster than the gear 530, and for this reason, the gear 530 can apply rotation to the shaft 520 through the overrunning clutch 531. The result is that the sprocket 529 carried by the shaft 520 is rotated at thermal imaging speed and thereby thermal imaging speed is applied to the mimeograph cylinder. Once the mimeograph cylinder is stopped in the positive stop position, because of the limited electrical power applied to the clutch 494 a slipping effect occurs, and the mimeograph cylinder, while having rotative power applied thereto, does not turn because it is not permitted to by the positive stop mechanism. However, once the positive stop mechanism is released then the thermal imaging drive is again applied to the mimeograph cylinder and the stencil is transferred to and laid on the mimeograph cylinder using the thermal imaging speed.

As has been noted, the thermal imaging speed can be adjusted. One reason for so doing is that different originals may require different exposure times. To this end, the idler pulley 569 is swingable between a position, shown in solid lines, for providing the slowest thermal imaging speed and another position, shown in phantom, for providing the maximum thermal imaging speed. For adjusting the position of the idler pulley 569, the latter is carried on an arm 595 which is pivotally supported on a pin 596. In the exemplary embodiment for swinging the arm 595 a hand crank assembly 598 is provided. The latter includes a support pin 599 for carrying a stirrup 600 and an adjusting link 601 attached by a pin 602 to the arm 595. The stirrup 600 rotatably anchors one end of a threaded adjusting shaft 604 which has a hand crank 605 provided at the opposite end. The link 601 has a leg 606 having a threaded aperture for receiving the threaded shaft 604. The link 601 is provided with a longitudinally extending slot 608 for receiving the support pin 599. Accordingly, as the threaded shaft 604 is turned by the hand crank 605 the leg 606 moves relative to the threaded shaft 604. The result is that the link 601 is moved relative to the support pin 599 and swings the arm 595 to locate the idler pulley 569 in various positions. The drive pulley 565, as has been explained, is adapted to vary in diameter with the tension on the belt 568. Thus, as the tension is changed by moving the idler pulley 569 selected speeds for the thermal imaging drive can be obtained. It would be within the knowledge of one skilled in the

art to adapt the above-identified thermal imaging speed system for automatic operation.

CONTROL SYSTEM

Turning to FIGS. 33 and 34, thereshown is an exemplary electrical schematic for the copier/duplicator 10. FIG. 33 shows the A.C. part of the system and FIG. 34 shows the D.C. part of the system. In the present instance a suitable source 620 of A.C. voltage, for example 115 volts, is connected between a pair of leads 620, 621. A set of main switches 624 having contact 624a, 624b, 624c and 624d are provided to initially energize a cooling subassembly herein shown as a blower motor 625 and the afore-mentioned main drive motor 500 and the pneumatic system motor 281a. The blower motor 625 is a part of the system for cooling the thermal imaging assembly 32 and operation thereof is controlled by a thermally responsive switch 626. The latter may take the form of a bi-metal switch which upon heating closes contacts to complete the circuit to the blower motor and upon cooling opens the switch to turn the blower motor off. The thermal switch is operative only when the thermal imaging assembly 32 is not being used. When thermal imaging is occurring, the blower motor is continuously energized through a contact CR1a and main switch 624a. Thus, during imaging the components of the imaging assembly are prevented from overheating and either being destructed or becoming inoperative.

The main switches 624 are operated preliminarily to operation of the machine. After the warm-up period the machine is ready to operate and a start push button 628 may be actuated. Closing of the latter enables the original sheet feeler switch 41 to be operative. The latter has contacts 629 which upon closing complete a circuit for a relay R1 through a set of normally closed contacts CR12. Energization of the R1 relay operates the associated contacts CR1a, CR1b and CR1c. Operation of contacts CR1a removes the thermal switch 626 from the circuit of the blower motor 625 and maintains the latter in continual operation. Contacts CR1b provide a bypass for the start push button 628 and the original feeler contacts 629. Closing of contacts CR1c completes the circuit to a power rectifier 630 which converts the A.C. voltage to a D.C. voltage for the D.C. part of the system, exemplarily shown as 24 volts D.C. The output of the rectifier 630 is applied to a pair of lines 631, 632.

At this point the main drive motor 500 is operating and drive is being transmitted through the main drive train to operate the main drive shaft 505 and provide drive input to the speed selector 506. As part of the preparation cycle the eject speed solenoid 555 is also energized through normally closed contacts CR4a when the start push button and original feeler switch were closed. That results in the speed selector 516 transmitting eject speed drive to the mimeograph cylinder as has been previously described. Also, reed switch 436 is enabled by application of D.C. voltage to lines 631, 632, so as to be ready to respond to the magnet 431 passing by as the mimeograph cylinder main gear 350 rotates. The reed switch 436, which initiates the operation of the eject assembly 40, is positioned a predetermined number of degrees ahead of the point at which the used stencil is to be picked up, in the exemplary embodiment approximately 45°.

In addition, at this time the coil 586 in the clutch 494 for applying a selectable torque thermal imaging drive to the mimeograph cylinder is energized at partial power in preparation for the positive stopping of the mimeograph cylinder after the eject of the used stencil has been completed. As is clear from FIG. 34, a rheostat 586a is connected in series with the coil 586 to adjustably limit current therethrough. The overrunning clutch 531 assures that eject speed, which is faster, is applied to the mimeograph cylinder instead of thermal imaging speed; thus preventing interference between drives, but having the lower terminal imaging speed ready for instant application to the mimeograph cylinder when the stencil is to be loaded on the latter.

As the mimeograph cylinder 36 makes its first revolution at eject speed, the magnet 431 actuates the reed switch 436 and thereby energizes relay R2 through normally closed contacts CR13 (See FIG. 34). Energization of relay R2 closes contacts CR2 and completes a circuit to relay R3. Energization of the latter closes contacts CR3a, CR3b and CR3c. Closing of contacts CR3a completes a holding circuit for relay R3 and also enables reed switch 439. Closing of contacts CR3b enables the reed switch 438 to energize relay R4 when the magnet 431, associated with the mimeograph cylinder 36, passes by. Closing of contacts CR3c effects energization of a relay R16 through normally closed contacts CR14b.

Energization of relay R16 closes contacts CR16a and CR16b. Closing of contacts CR16a energizes a coil 354a comprising a part of the take-up system drive clutch 354. Accordingly, drive is applied to the eject or take-up assembly 40, and specifically to the main eject drive shaft 311 from which drive is applied through chains and gears to the positive feed rollers 326, 328 and the wind-up roll 42. The latter is driven through the O-ring slip clutch 354 to assure a tight wrapping of the used stencil between layers of the web. As is clear from the above, the captivating web is driven after the mimeograph cylinder associated magnet 431 has actuated reed switch 436. As can be appreciated from viewing FIGS. 13, 14, 15 and 25, the orientation of the reed switch 436 to the receiving point or catching zone of the eject assembly is such that the forward end 109a of the stencil is approximately $\pi/6$ radians short of arriving at the eject assembly when the reed switch 436 is actuated. Thus, there is a short period of time during which the web is being rolled up on the take-up roll 42, without any stencil being present between layers. Thus, the exemplary structure provides a separation between respective sheets of used masters wrapped in the wind-up roll.

As has been explained, it is necessary to detach the stencil leading end 109a and direct it into the catching zone of the take-up assembly 40. In the exemplary embodiment that is effected by operating the valve 280 into the mode shown in FIG. 12A. To that end, closing of contacts CR16b completes an energizing circuit for valve operating relay or solenoid 287. The latter when energized actuates the spool 290 in a position as represented in FIG. 12A, so as to direct air flow out of the apertures 261, 262 and 263 and detach or blow away the stencil end. When the solenoid 287 is de-energized, the valve is spring biased to a normal position as represented in FIG. 12B, drawing air into and through the apertures 261, 262 and 263.

As explained, closing of contacts CR3a enables or makes operative the reed switch 439. The latter is positioned a predetermined number of degrees beyond the eject cycle initiating reed switch 436, in one practical application approximately 180°. The mimeograph cylinder carries the magnet 431 around with it as the clinging, used stencil is peeled off by the eject assembly. After the stencil has been removed the magnet applies an actuating magnetic field to switch 439. Actuation of the latter energizes relay R14 which actuates contacts CR14a and CR14b. Contacts CR14a are closed to provide a holding circuit for relay R14 and contacts CR14b are opened to de-energize relay R16 which opens contacts CR16a and CR16b. Opening of contacts CR16a de-energizes the take-up web main drive clutch coil 354a terminating operation of the eject assembly 40, and opening of contacts CR16b de-energizes the air valve solenoid 287 permitting the spool 290 to return to the position shown in FIG. 12B so that air is drawn into the stencil clamp apertures 261, 262, 263.

After almost a complete revolution following the initiation of the eject assembly drive by actuation of reed switch 436, the reed switch 438 is actuated and relay R4 is energized. Energization of relay R4 actuates contacts CR4a, CR4b. Actuation of contacts CR4a de-energizes the eject speed solenoid 556 and initiates a function cycle by energizing a control sub-circuit 634. The latter enables the master cam 475 to rotate through one revolution and effect sequential operation of machine functions to feed the original and stencil, image the stencil, transfer an end of the stencil to the mimeograph cylinder and cut off the proper length of stencil material, strip the original from the transfer cylinder and place the machine in readiness for the print cycle.

Closing of contacts CR4b completes an energizing circuit to relay R13 which actuates contacts CR13 to disable reed switch 436 and enables a contact CR11c, the operation of which is described subsequently. Accordingly, the subsequent actuation of the reed switch 436 by magnet 431 will not have an effect on the control circuit.

In the exemplary embodiment, the master cam is driven through a single revolution clutch. As has been described, in the exemplary embodiment the latter is a spring clutch similar to clutch 226 shown in FIG. 9 which assures one complete revolution of the master cam once it is actuated bringing the cam wheels 478-482 to their starting position at the end of the single revolution. Describing the sub-circuit 634 and the operation of the master cam assembly 475, upon actuation of contacts CR4a a circuit is completed through normally closed contacts CR9b, normally closed microswitch contacts MS1 and relay R6. Accordingly, the latter is energized, closing contacts CR6a, CR6b, and CR6c. Closing of contacts CR6c energizes a solenoid 487f to apply drive to the master cam and start rotation of the cam wheels 478-482.

Because initially cam wheel 478 of the master cam has a high portion of the cam wheel acting on the follower arm of the microswitch M1, the microswitch contacts MS1 are closed. As has been explained, the result is a completed circuit energizing relay R6.

The closing of contacts CR6a energizes the frame lowering solenoid 384 which unlatches the cam follower 370 and permits the upper portion 20 of the machine

to pivot under the control or drive provided by the frame lowering arm 386 following the peripheral surface of cam 386.

Simultaneously the positive stop solenoid 46 is energized by closing of the contacts CR6b. As a result, the cam follower 402 is released and the cam follower wheel 404 is engaged with the positive stop cam 392. At this time, the cam 392 is rotating with the mimeograph cylinder 36 and is coasting down from eject speed, the eject speed solenoid having been de-energized, and imaging speed drive is applied through the electric clutch 494 and the overrunning clutch 531. As described in one practical instance, the current in the electric clutch coil was adjusted to about 50 per cent of normal level. When the follower wheel 404 drops into the pocket 392b, the cam pressure angle is so great, well over 45°, that the follower wheel 404 cannot be lifted. The torque transmitted through clutch 494 is sufficient to hold the wheel 404 in the pocket 392b so as to hold the mimeograph cylinder 36 in precisely the desired position.

A relay R5 is also energized through the normal position of contacts CR9c and initially closed contacts MS4 of microswitch M4 so that its contacts CR5 are closed to complete a circuit to the thermal imaging lamp 168. The duration of the operation of the imaging lamp 168 is controlled by master cam wheel 480. The master cam wheel 479 is also initially positioned so that the switch cam follower for the microswitch M2 is actuated by a high on the cam wheel 479, and the microswitch contacts MS2 are closed so as to complete a circuit to a master web feed clutch coil 130a through normally closed contacts CR8c and actuated contacts CR4b. As already described, the master web feed rollers 111, 112 rotate to feed the master web along a bed 110 past a knife assembly 139 and on to the stencil transfer conveyor 151.

The cam wheel 479 has a high portion for actuating the other microswitch M3 at the correct time. Closing of contacts MS3 completes a circuit to the original feed solenoid 86. As has been described, operation of the latter lowers the stop fingers 79 and presses the upper roller 65 against the capstan roller 64 to feed the original along a predetermined path. The operation of the stencil web feed and the original sheet feed are timed so that when the web and sheet arrive at the thermal imaging station 32, in the exemplary embodiment the stencil leads or precedes the lead edge of the original document or, if a carrier is used, the lead edge of the carrier by approximately $\frac{1}{8}$ th's to $\frac{1}{2}$ of an inch.

The sandwich comprised of the original or an original carrier and the stencil are fed to the belt 74 and thermal imaging insulating tube 169. The infra-red source 168 is turned on by energization of the relay R5 and closing of contacts CR5, as has been explained, and thus imaging of the stencil by the original is effected.

At this time cam wheel 478 also actuates a follower carried by microswitch M7 to close contacts MS7, and thus to complete a circuit through relay R7. Energization of the latter actuates contacts CR7a and CR7b. Closing of contacts CR7a energizes the positive stop release solenoid 418. The result is that lever 408 is actuated to raise the cam follower wheel 404 out of the cam pocket 392b at precisely the right time and permit the mimeograph cylinder to rotate at thermal imaging speed. It will be recalled that the stencil is also traveling toward the mimeograph cylinder at thermal imaging

speed. Closing of contacts CR7b energizes relay R10 which actuates contacts CR10a, CR10b. Closing of contacts CR10a provides a holding circuit for relay R10 and closing of contacts CR10b by-passes the rheostat 586a to apply full power to clutch coil 586.

The master cam is coordinated with the operation of the machine so that at this point the sandwich of the original and master has been carried to the transfer roller 202, in the present instance, a pneumatic system that provides a segmental zone of attractive force drawing the sandwich against the outer transfer cylinder 204. The outer cylinder 204 is being continually rotated at thermal imaging speed while the machine is operating. The inner valving cylinder 216 remains stationary with the slots 218 defining an arcuate area of partial vacuum about the surface of the outer cylinder 204. As noted the exemplary embodiment has an arcuate segmental zone of attractive force subtending approximately 127°, however, other size segmental zones may be utilized, the object being to carry the original and stencil sandwich from the thermal imaging assembly 32 to the stencil grasping and holding assembly 39 of the printing form. The foregoing size segmental zone assures that the sandwich is picked up when it exits from the chute opening 189 and is carried to a position for grasping by mimeograph stencil clamp 250. At the time that the sandwich is being carried by rotation of the transfer cylinder assembly 202, the latter has been already lowered into the mimeograph cylinder void 36b under the control of the frame lowering cam 386. The stop motion diagrams of FIGS. 24A-24C represent that phase of machine operation. The energization of the positive stop release solenoid 418 is timed to occur so that the stencil clamp 250 arrives at the correct position to permit the partial vacuum applied to the mimeograph cylinder clamp apertures 261-263 to draw the stencil end into the slot formed on the stencil clamp surface. The valving cylinder 216 and slots 218 thereof, terminate the segmental zone of attractive force so that as the outer cylinder carries the sandwich beyond slot lower end 218a, the attractive force is removed from the stencil forward end 109a and the stencil end is brought into a grouping zone for pick up by the mimeograph clamp. Accordingly, the $\frac{3}{8}$ th's to $\frac{1}{2}$ inch long end of the stencil loses its attraction or partial vacuum influence from the transfer cylinder assembly 202 and the grasping action of the air flow into clamp apertures 261-263 draws the stencil to the mimeograph clamp 250.

To separate the original from the stencil and carry it around and into a tray 38, the inner valving cylinder 216 is permitted to rotate with the outer cylinder 204 after the end of the stencil has been grasped by the mimeograph cylinder clamp 250. To that end, cam wheel 481 actuates microswitch M6 and closes contacts MS6 to energize transfer valve solenoid 240. As has been described, energization of the latter releases the barrel 232 on the spring clutch 226 and permits drive to be coupled to the inner valving cylinder 216 so that the partial vacuum circumferential portion of the outer cylinder 204 is moving with rotation of that cylinder. The result is that the original is held under the influence of the moving vacuum area and brought up against stripper fingers 244 and a stripper roller 243 to be stripped off and directed into the tray 38.

To assure the proper length of stencil to cover the ink pad area of the mimeograph cylinder, the cam wheel

481 actuates microswitch M5 to close contact MS5 after the desired length of stencil material has been paid out from the stencil supply roll 105. In the exemplary embodiment, closing of contacts MS5 applies power to a power supply 636 which energizes the stencil cut-off electrical coil 143c. As has been explained, the stencil cut-off solenoid 142 operates the stencil cutting knife blade 140.

As the last step in the operation of the master cam 10 475, the cam wheel 482 actuates microswitch M8 and closes contacts MS8 to energize relay R8. Energization of the latter closes contacts CR8a, CR8b, and opens contacts CR8c. Closing of contacts CR8a provides a holding circuit for the relay R8. Closing of contacts 15 CR8b energizes the print speed solenoid 555, and the opening of the contacts CR8c de-energizes the stencil feed clutch coil 130a. Accordingly, the stencil has now been wrapped about the mimeograph cylinder 36 and the speed of the mimeograph cylinder is raised to the 20 print speed.

Because cam wheel 478 upon returning to its starting position would again actuate the frame lowering solenoid 384, the positive stop solenoid 416 and the master cam single revolution clutch 494a, it must be disabled 25 at the end of the master cam single revolution. To that end, the microswitch M9 is operated said contacts MS9 are closed. Closing of the latter energizes relay R9 to close contacts CR8a, to open contacts CR9b and to actuate contacts CR9c to complete a circuit to a paper feed solenoid 639. Closing of contacts CR9a provides a holding circuit for the relay R9. Opening of contacts CR9b assures that relay R6 is not energized when master cam wheel 478 closes contacts MS1 after one complete revolution of the master cam wheels. Thus, energization is prevented of the frame lowering solenoid 384, the positive stop solenoid 416 and the master cam single revolution clutch coil 487f. Contacts CR9c in the actuated position deenergize relay R5 to open contacts 30 CR5 and break the circuit to lamp 168. Also, contacts CR9c in their actuated position, through normally closed contacts CR11b, energize the paper feed solenoid 639 to initiate operation of the paper feed assembly 48 and feed sheets of paper from a stack 46 into the crotch between the impression roller 49 and the mimeograph cylinder 36. The followers of microswitches M8 and M9 are coupled together so that cam wheel 482 operates both of them at the same time. Thus, it can be understood from the foregoing that the reproduction system is sequenced through a preparation 35 cycle in which the printing form is operated in eject mode, a function cycle under the control of the master cam in which the printing form is operated in a thermal imaging mode, and then in a reproduction or print cycle in which the printing form is operated in a print mode.

A safety system is provided in the form of a partial vacuum switch 640. The latter is coupled to the pneumatic system shown in FIGS. 12A and 12B. The vacuum switch is provided with a set of contacts 640a which are normally held open if a partial vacuum or reduced pressure is present in the conduit 269. However, should there be a failure in the system and for some reason the partial vacuum is not provided at the clamp 250, then the contacts 640a are closed and a relay R11 is energized. Energization of the latter closes contacts CR11a thereby holding the relay R11 energized and opens contacts CR11b and closes contacts CR11c.

Opening of contacts CR11b de-energizes the paper feed solenoid 639. Closing of contacts CR11c enables the reed switch 436 to energize relay R12. Energization of relay R12 opens contacts CR12 to de-energize the relay R1 and shut down the complete control circuit.

After the desired number of copies have been made during the print cycle or mode of machine operation, a copy count responsive set of contacts 641 are actuated. The actuation of the latter also completes an energizing circuit for the afore-described relay R11 through the actuated contacts CR9a. Accordingly, an operation terminating sequence is initiated the same as the afore-described emergency or safety stop sequence. The use of the reed switch 436 to energize the relay R12 and providing a predetermined time delay in the latter assures that mimeograph cylinder rotation is terminated so that it stops with the refill opening 260a pointing downwardly and the mimeograph cylinder control magnet 431 positioned generally as shown in FIG. 25. The used stencil is wrapped about the ink pad so as to cover the upper half of the cylinder when the latter is at rest with its axis generally horizontally oriented. This is the well-known rest position for a mimeograph cylinder to prevent seepage while the mimeograph cylinder is sitting unused. As noted, the latter position is also the position in which machine operation begins when the old stencil is to be ejected and a new stencil is to be mounted on the mimeograph cylinder.

OPERATION

To describe an overall sequence of operation of the copier/duplicator 10, reference is made to the sequence diagrams of FIGS. 35 and 36. FIG. 35 represents the preparation cycle, during which the printing form is operated in the eject mode. An abscissa is divided into degrees of mimeograph cylinder rotation, also transposable into inches of cylinder surface travel. In one practical example the mimeograph cylinder had a circumference of approximately 30 inches. The function cycle, during which the printing form is operated in the thermal imaging mode, and the print cycle, during which the printing form is operated in the print mode, are represented in FIG. 36. The abscissa in that instance is in terms of inches of stencil travel. The function cycle is timed to start after approximately 462° of mimeograph cylinder rotation in the exemplary embodiment. Thereafter, through the preparation cycle and the function cycle overlap they are not commonly controlled.

Turning to FIG. 35 and a description of the preparation cycle, when the main switch 624 is operated, the main drive motor 500 is energized, the pneumatic system motor 281a starts and the valve 280 is in an unactuated state so that air is being drawn through apertures 261-263 of the clamp 250. The eject speed solenoid 556 is energized so that eject speed drive is coupled to the mimeograph cylinder from the main drive motor 500.

The mimeograph cylinder turns, in the exemplary embodiment, for approximately 6 142°, or with the above-noted size mimeograph cylinder, approximately 10 inches, whereupon reed switch 436 is actuated by magnet 431. As has been described, the reed switch 436 is located a predetermined angular distance ahead of the used stencil input to the eject or take-up assembly 40. The latter is generally shown in FIG. 15 and the afore-mentioned angle between reed switch 436 and

the eject assembly input point is approximately 25° because the clamp apertures 261 are approximately 25° ahead of the actuating magnet 431. Thus, as the used stencil is being carried by the mimeograph cylinder, approximately 25° before the used stencil is to be grabbed or taken up by the eject assembly 40, the valve 280 is actuated in response to reed switch 436 being operated to effect forcing out of air at the mimeograph cylinder clamp 250. Simultaneously drive is coupled to the main eject drive shaft 311 to effect take-up web advance. Thus, the end of the stencil is blown away from the cylinder clamp 250 and into the mouth or take-up of the web path to be wrapped about the web take-up roll 42 between layers of material.

The eject cycle continues for a sufficient period of time to peel the used and soiled mimeograph stencil from the mimeograph cylinder 36. In the exemplary embodiment, that is until the mimeograph cylinder reaches a 330° point from the cylinder start or reference. That also is approximately 15 inches of cylinder travel after the eject cycle has started. To that end, in the exemplary embodiment, the reed switch 439 is located approximately 188 degrees beyond the eject cycle initiating reed switch 436. Thus, when the magnet 431 passes by reed switch 439 drive to the eject system web is terminated by de-energizing the electric clutch 354, and though the cylinder 36 is being driven at eject speed the eject cycle is over. The pneumatic valve 280 is also de-energized by actuation of reed switch 439, thereby re-establishing the normal condition of air being drawn toward the mimeograph cylinder clamp 250. As explained, the eject speed solenoid 556 is not de-energized until the magnet 431 passes by reed switch 438, the latter being positioned at approximately a 462° point. The function cycle begins with the actuation of the reed switch 438.

Because eject speed is higher than thermal imaging speed, though drive is applied to overrunning clutch 531, until the mimeograph cylinder coasts down to thermal imaging speed no drive is transmitted through clutch 531 to the mimeograph cylinder. However, the mimeograph cylinder is assured of positive drive at thermal imaging speed into the positive stop position, which in the exemplary embodiment is shown as approximately a 612° point with respect to the start or reference.

Turning now to FIG. 36 and a description of the function cycle, each occurrence in the function cycle is made with reference to distance of stencil travel by that point in time.

First, the operation of the master cam 375 is initiated by operating the single revolution clutch 479. Also initially, the microswitch M4 controls power flow to the thermal lamp, the microswitch M3 effects feeding of the original, and the microswitch M2 initiates operation of the stencil feed. As explained, actuation of reed switch 438 at the start of the function cycle also energizes the frame lowering solenoid 384 and the positive stop engagement solenoid 416 to simultaneously initiate frame lowering and set-up the positive stop mechanism. The operation of the thermal lamp, the original feed and the stencil feed is controlled by the cam wheels associated with the microswitches M4, M3 and M2. In the exemplary embodiment wherein an 11 inch original is used, the thermal lamp is maintained on for approximately 20 inches of stencil travel, the additional time/distance allows the imaging lamp to warm-up. The

original is fed for approximately 15 inches of stencil travel and the stencil positive feed is maintained for approximately 13 inches of stencil travel. After approximately 7½ inches of stencil travel the positive stop is released by the microswitch M7 which at the same time effects application of full power to the thermal imaging drive clutch 494 to drive the mimeograph cylinder at thermal imaging speed. The stencil is picked up by the mimeograph cylinder clamp 250 on the fly after approximately 10 inches of stencil travel. At that same point in time the original is stripped from the stencil by operation of the transfer assembly 35. In the present instance, the clutch 226 associated with the transfer cylinder assembly 202 permits the inner valving cylinder 216 to rotate with the outer cylinder 204 and carry the original around the transfer roller to a set of stripping fingers 244 and a stripping roller 243 to be ejected into an original receiving tray 38. As that is occurring, the transfer cylinder assembly 202 and the stencil end is being raised slightly by portion 386d of the upper frame driver or cam 386 following the contour of clamp 250. The mimeograph cylinder is of course rotating at thermal imaging speed and carries the clamp 250 having the apertures 261-263 through which air is being drawn. The stencil end 109a is grasped and held in a slot 266 as shown in FIGS. 7A, 24B and 24C. In this manner the stencil is automatically laid on to the mimeograph cylinder.

Grasping zone 399 may be generally located by determining the relative positions of the transfer assembly 35 and the printing form 36. It may be more precisely defined by the control over the movement of the transfer assembly 35 and the setting of the inner valving cylinder 216 in relation to the outer cylinder 204. This can be appreciated from FIG. 24B. As the outer roller 204 rotates and carries the sandwich of the original and stencil, the slot termination position 218a is reached. Transport of the sandwich beyond the slot termination line places the forward end of the sandwich into a peripheral region where the inner cylinder 216 cuts off the partial vacuum or drawing of air through the outer cylinder 204. Accordingly, the stencil end 109a is not held by air drawn into the transfer roller 204, but instead is free so that the mimeograph cylinder clamp 250 can grasp it. By angularly adjusting the inner cylinder 216 relative to the outer cylinder 204, end 218a of the segmental zone of attractive force can be selected. To that end, the mounting yoke 230a is provided. In the exemplary instance, a carrier was used with the original, thus the actual original end is even further behind the forward end of the stencil 109a than if the sandwich is comprised only of a stencil and original. The purpose, in the exemplary embodiment, is to image the stencil so that it registers with the printing area of the mimeograph cylinder. As can be noted from FIG. 10, the ink pad 258 starts a predetermined spaced angularly distance from the point at which the stencil end is picked up by the clamp pneumatic slot 266.

After 14 inches of stencil travel, microswitch M5 operates rotary solenoid 137 to actuate the knife 139 and cut the stencil. Of course, if precut sheets of stencil were being used, stencil cutting would not be necessary. As will be noted, the feeding out of stencil material was stopped after 13 inches of stencil travel and cutting of the stencil is shot effected until after 14 inches of stencil travel. This is in order to stretch the stencil in the area of the stencil cutting knife assembly

139 and facilitate cutting the stencil. In the present instance, the transfer cylinder assembly 202 for stripping the original from the stencil has the inner cylinder 216 rotating with the outer cylinder 204 for one complete revolution under the control of the spring clutch 226. Using the exemplary size transfer outer roller 204, that is equivalent to 11 inches of stencil travel, which assures that an 11 inch original and carrier are stripped off the roller and placed in the original tray. The valving cylinder 216 then returns to its start position and the single revolution clutch removes drive to hold it there.

After 24 inches of stencil travel microswitch M8 effects energization of the print solenoid 555 and microswitch M9 effects energization of the paper feed solenoid 639. At that point the laying down of the stencil on the mimeograph cylinder has been completed. The distance of stencil travel before the system goes into the print cycle is determined by the total path length which the stencil must travel plus the required length of stencil.

The master cam continues to rotate until a point represented by 30 inches of stencil travel whereupon the microswitches M1-M9 return to their starting positions. It is of course understood that the location and movement of the cam wheels 478-482 and microswitches M1-M9 have been empirically related to the stencil transport so that the foregoing stencil travel distances can be related to machine operations. In the present instance there is no sensing of length of stencil travel however that could be used to control machine operation.

Subsequently the copier/duplicator is in the print cycle with the machine producing mimeograph copies on ordinary paper, one copy being produced with each rotation of the mimeograph cylinder. After the desired number of copies have been printed, a copy count satisfying switch is operated either manually or automatically closing contacts 641 which stop machine operation. As has been described, the mimeograph cylinder is stopped in a position so that the used stencil is facing upwardly and the ink inside the mimeograph cylinder is located in the bottom of the mimeograph cylinder to assure non-leakage of ink through the cylinder diaphragm. This is because the relay R12 is a time delay relay which continues machine operation in the print cycle for a pre-set period of time after the signal is given to stop the machine.

Though the foregoing description has defined a particular copier/duplicator utilizing a film stencil material carried in a roll form, the principles of the present invention are applicable to other forms of mimeograph stencil sheets. For example, pre-cut sheets of stencil could be used. It is not necessary that the stencil be formed on the same machine. The stencil may have been formed previously and be fed through the machine for automatic transfer to the mimeograph cylinder. The used stencil can be automatically ejected. Also, though a particular form of the used stencil take-up assembly has been described, other equivalent forms in which a stencil is disengaged from the mimeograph cylinder and caught in a take-up or an eject assembly may be utilized. For example, a simple pair of grabbing roller expending the used stencil into a receiving container may be used. In this same vein, though a particular arrangement for transferring the stencil pneumatically to the mimeograph cylinder pneumatic

clamp has been described, mechanical arrangements for laying down the stencil end of an equivalent nature may be used. In addition, though a cylindrical printing form is exemplarily shown, other forms of mimeograph printing forms may be used.

I claim as my invention:

1. A sheet transfer system for transporting a pair of sheet members sandwiched together with a lead edge of the first sheet forward of the lead edge of the second sheet to separate, predetermined locations, respectively, said system including in combination: a member mounted for rotation, said member including an outer porous cylinder and air flow means to provide an attractive force for drawing said sandwiched pair of sheets against the periphery of said cylinder as the latter rotates, said first sheet comprising the outer sheet of said sandwiched pair, whereby said drawing means acts only on the lead edge of said first sheet for attracting the first sheet to the periphery of said cylinder, said sandwiched sheets being drawn to the periphery of said cylinder at a first, home position and carried thereby in the direction of rotation thereof along a path about the outer periphery of said cylinder, valving means included in said cylinder for releasing said attractive force, and means for controlling said valving means to selectively remove said attractive force only from the lead edge of said outer sheet upon the latter being carried to a first location downstream of said home position, thereby releasing said sheet for travel along a separate path away from said cylinder, said valving means being effective to maintain said attractive force on said second, inner sheet for transporting said lastmentioned sheet on said cylinder to a second location about the periphery thereof, downstream of said first location, whereat said second, inner sheet is removed from said cylinder.

2. The combination of claim 1 including means provided at said second location for stripping the second, inner sheet from said cylindrical member and directing it in a separate second path.

3. The combination of claims 1 wherein said outer porous cylinder includes selective peripheral portions

coupled to said air flow means to define a segmental zone of attractive force; and said valving means includes an inner selectively rotatable cylinder concentric with said outer cylinder having openings to control communication between said air flow means and said outer cylinder peripheral portions; and said control means includes means for effecting relative rotation between said outer and inner cylinders for selectively adjusting the position of said segmental zone of attractive force in accordance with the rotational position of said outer cylinder while transporting the sheet sandwich about the outer cylinder periphery.

4. The combination of claim 3 wherein said inner cylinder is rotatable with said outer cylinder for moving said segmental zone of attractive force with transport of the sheet sandwich.

5. The combination of claim 4 wherein said means for effecting relative rotation between said outer and inner cylinders maintains said zone of attractive force in fixed orientation until the leading end of the first, outer sheet is transported beyond said zone of attractive force a predetermined amount and the second, inner sheet substantially overlies said zone, whereupon said selective rotation effecting means initiates movement of said segmental zone of attractive force.

6. The combination of claim 3 wherein said outer cylinder includes a central shaft means for mounting said cylinder for rotation and said inner cylinder includes central shaft means mounted within said outer central shaft means concentrically therewith and wherein said means for effecting relative rotation between said outer and inner cylinders includes means for coupling and decoupling said outer and inner shafts whereby said inner cylinder is made to rotate or remain stationary with respect to said outer cylinder, said coupling-decoupling means including spring means wrapped about said outer shaft and connectible with said inner cylinder central shaft means upon being coiled, and means coupled to said spring means for coiling and uncoiling said spring means in accordance with the rotational position of said outer cylinder.
